MACHINE FOR PRESSING SOLES ON SHOES

Sidney J. Finn, Beverly, Mass., assignor to United Shoe Machinery Corporation, Paterson, N. J., a corporation of New Jersey

Application September 29, 1932, Serial No. 635,397
In Great Britain September 13, 1932

133 Claims. (Cl. 12—37)

This invention relates to machines for use in the manufacture of shoes and is illustrated herein as embodied in a machine for use in the cement attachment of soles to shoes.

5 In the attaching of soles to compo shoes, it is the usual practice to roughen the marginal face of the sole, apply cement thereto, and allow it to dry. The overlasted margin of the upper is also roughened, similar cement applied thereto, and allowed to dry. Before relatively locating the shoe and the sole and placing them under pressure, a softener is applied to the cement on the sole and the shoe bottom, or to the cement on one of those parts, preferably on the sole, which softener activates the cement and causes the shoe and sole to adhere permanently to each other after the application of pressure for a suitable time, formerly from twenty to thirty minutes.

Recent developments in the art, such, for example, as that disclosed in Letters Patent of the United States No. 1,959,321 granted May 15, 1934, upon an application filed in the name of Walter H. Wedger, have produced softeners by the use of which the time during which the shoe need remain under pressure has been greatly shortened, so that the number of devices in use at one time for maintaining the shoes and soles under pressure may be greatly reduced.

A general object of this invention is to provide an improved machine for pressing together shoes and soles which will be thoroughly effective in obtaining contact under reasonable pressure between the shoes and soles at all portions which are to be united. The illustrated machine is capable of large production and is particularly convenient under conditions such that the pressure need not be maintained for a great length of time.

Other objects are to insure that a predetermined pressure will be applied to each shoe, and to insure that the machine controls will be operated in the proper order.

Further objects of the invention are to provide improved means for relatively locating the shoe and sole prior to the application of pressure, to render the introduction of the shoe and sole into the machine and the removal of the shoe from the machine easy and convenient, and to provide sole pressing pads with improved means for readily varying the longitudinal curvature or profile of the pad to meet different conditions of work presented by different shoes to which soles are to be attached.

With these objects in view, a feature of the invention consists in an organization compris-

ing a carrier arranged for intermittent movement past an operating station and a plurality of pads on the carrier arranged with their sides, that is, with one of their longer sides, toward the operator. As illustrated, the carrier is a turret mounted for rotation about a vertical axis and the pads are arranged with their long axes tangent to the path of rotation of the turret.

Another feature of the invention consists in abutments or holdowns for the shoes, each comprising a toe rest and a heel rest arranged for movement from a position where they are not over the pad into operative position over a shoe on the pad from that side of the pad which is remote from the operator. As illustrated, the abutments move radially of the turret into and out of position over the pads and are carried by balls mounted for swinging movement about axes located below the pads and extending lengthwise thereof.

As another feature of the invention, fluid-pressure-operated means is provided for effecting vertical movement of the abutments to apply pressure to the shoe. As illustrated, an expandable member is provided between a fixed support for the pad and a member, carried by the axis on which the abutment is mounted, expansion of which by fluid pressure moves the abutment toward the pad to press a shoe thereon.

A further feature of the invention consists in a pump mounted on the turret and rotatable therewith for supplying fluid under pressure to the fluid-operated means. Preferably, and as illustrated, the pump is operated prior to and during each step of rotation of the turret and is brought to a stop at the end of each step. This construction avoids the use of rotary or slip joints between the turret and a stationary source of fluid supply. In the illustrated machine each fluid-operated means is provided with a valve having inlet and outlet positions controlling the admission of fluid from the pump to the fluid-operated means and exhaust of fluid therefrom.

As a further feature of the invention, operator-controlled means is provided at the operating station for moving each valve to inlet position and thereafter setting the pump in operation.

In accordance with further features of the invention, the operation of the pump and the rotation of the turret are controlled by separate clutches, and means dependent for its action on rotation of the turret is provided for moving each valve in turn to exhaust position as it approaches the operating station. As illustrated, pressure is relieved from the pad next to come to the operat-

ing station simultaneously with the application of pressure to a shoe at the operating station, these actions taking place preferably while the mechanism for rotating the turret is in motion.

5 Another feature of the invention consists in novel means for adjusting the support of the forepart of the pad to vary the angular relation of the forepart and the shank portion of the pad and for insuring that the support will remain in place after such adjustment has been effected.

10 Another feature of the invention consists in a suitably mounted pin for locating the rear end of the sole which preferably engages a hole in the lateral center of the sole. As illustrated, the pin is mounted upon a tongue movable bodily longitudinally of the pad and restrained from movement laterally thereof. Preferably the tongue is arranged to swing heightwise of the 15 sole to facilitate engagement of the pin with the hole in the sole to locate the rear end of the sole laterally with respect to the pad.

15 Another feature of the invention consists in forepart sole gages arranged for movement into and out of operative position laterally of the pad and having only a slight movement longitudinally of the pad. Preferably the gages contact with the sides of the sole at points approximately at the end of the tip line and at the ends of the ball 20 line and are provided with shoe gages by which the shoe is located in proper relation to the sole.

25 In accordance with a further feature of the invention, forward movement of the shoe is utilized to lock the gages against separation. As illustrated, members carried by the gages have teeth arranged to engage teeth formed upon a fixed member, forward pressure of the shoe against the gages causing slight longitudinal movement of the gages with consequent engagement of the 30 teeth and locking of the gages.

35 Another feature of the invention consists in an extensible sheet connecting the gages on one side of the shoe with the gages on the other side of the shoe, the gages being separated against the tension of the extensible sheet to permit introduction of the sole and being brought into engagement with the sole by contraction of the sheet. In the illustrated machine, means operated by rotation of the turret is provided to effect separation of the gages, and manually operated means is provided for permitting the gages to engage the sole. The extensible sheet may be made of rubber reinforced at its edges and, in accordance with another feature of the invention, the sole gages may extend through the rubber sheet to prevent the edges of the sole from 40 passing under them.

45 Still another feature of the invention consists in means operated by pressure of the shoe upon the pad for locking the gages in operative position. As illustrated, plates, preferably perforated, are connected with the gages and extend under the forepart of the shoe between the sheet and the pad so that pressure of the shoe upon the 50 pad will lock the plates against movement and thus prevent separation of the gages.

55 Still another feature of the invention consists in novel means for locating the rear end of the shoe with respect to the sole. As illustrated, 60 equally and oppositely movable members are arranged to engage opposite sides of the rear end of the shoe to centralize the rear part of the shoe with respect to the rear part of the sole as determined by the sole locating pin. Preferably 65 movement of the rear part locating members into

operative position is controlled by manually operated means which, as illustrated, may be the means by which the shoe engaging device or abutment is swung over the shoe.

70 Still another feature of the invention consists in a single manually operated means for controlling the operation of the gages, for moving the shoe engaging abutment into operative position, for turning the valve, and for operating the clutches which control the pressure applying means and the rotation of the turret, in proper sequence. As illustrated, the manual means consists of a treadle which permits movement of the shoe and sole forepart gages into operative position and movement of the gages for the rear part of the shoe into operative position. It then moves the shoe engaging abutment over the shoe and turns the valve at the operating station to inlet position. The treadle then becomes disconnected from these devices and, upon further movement, operates the clutch for starting the pump and the clutch for setting the turret rotating mechanism in operation. Disconnection of the clutches is, as illustrated, controlled by rotation of the turret without regard to the position of the treadle.

75 The above and other features of the invention will appear more fully from the following description when read in connection with the accompanying drawings and will be pointed out in the appended claims.

In the drawings:

Fig. 1 is a front elevation of the machine in which the present invention is embodied, with parts of the structure broken away to illustrate 80 details;

Fig. 2 is a side elevation of the machine shown in Fig. 1, with parts of the frame and the turret shown in section;

Fig. 3 is a plan view of the machine;

Fig. 4 is a plan view of a part of the mechanism of the machine below the supporting column;

Fig. 5 is a plan view, partly broken away and partly in section in a plane just below the turret 45 table, to illustrate the turret rotating mechanism;

Fig. 6 is a detail view in side elevation and on an enlarged scale, illustrating how several of the treadle controlled mechanisms are actuated by 50 the treadle;

Fig. 7 is a vertical section through the fluid pressure controlling means;

Fig. 8 is a vertical section through one of the pad boxes of the machine, showing, on an enlarged scale, a shoe mounted on a pad and the mechanism by which pressure is applied to the 55 shoe;

Fig. 9 is a plan view of the pad box shown in Fig. 8, illustrating in more detail the sole and 60 shoe positioning means;

Fig. 10 is a detail perspective view of the under side of a portion of the forepart positioning means;

Fig. 11 is a perspective view of the upper side 65 of the forepart positioning mechanism shown in Fig. 10; and

Fig. 12 shows in detail the means for actuating the forepart positioning means.

The illustrated machine comprises a frame 70 having a base 12 and a casing 14 above the base for enclosing mechanism of the lower portion of the machine. Above the casing 14 the frame projects upwardly to form a hollow column 16 which supports a rotatable carrier comprising 75

5 a circular turret or table 18 having a downwardly projecting hub portion 20 resting on a ball bearing 22, interposed between the hub and the upper end of the supporting column 16 to permit free rotation of the turret about a vertical axis. The turret 18 is held on the frame in vertical alignment with the column 16 by an elongated, hollow sleeve 24 which passes through the hub 20 of the table and extends downwardly 10 through the column 16, the sleeve being rotatably mounted in the column and being supported in the machine by an annular flange 26 (Fig. 7), projecting horizontally from its upper end and bearing against the upper surface of the turret 15 table 18. The lower portion of the sleeve is reduced in diameter and extends into the casing 14 to serve as a mounting for mechanism hereinafter to be described. A bushing 25 is mounted in the column 16 below the ball bearing 22 20 to provide a bearing for the rotatable sleeve 24.

25 The surface of the turret table 18, as seen in plan view, (Fig. 3) has six large openings 28 formed therein which serve to lighten the table, and solid portions 30 between the openings 28 extend radially from a solid central portion of the table which surrounds the opening at the hub. Beyond the openings 28 the surface of the turret table drops abruptly to form a vertical shoulder 32 which extends completely around 30 the table and, extending horizontally from the bottom of the shoulder 32, is a shelf 33 upon which is mounted a plurality of presser units or 35 pad boxes 34, six boxes being used in the present instance, which are spaced equidistantly around and bolted to the upper surface of the shelf 33. Each of the pad boxes is constructed and arranged to receive a shoe and sole and is positioned on the shelf 33 with its long axis at right 40 angles to a line extending radially from the center of the turret 18 to bisect said axis. The lengthwise dimension of the pad boxes, therefore, will be substantially tangential to the direction 45 of rotation of the turret table and the boxes will be presented sidewise to an operator as they are moved into an operating station at the front of the machine. The turret 18, sleeve 24, and mechanism mounted thereon are rotated with an intermittent motion to present each pad box successively at the operating station by mechanism 50 which will now be described.

55 A motor drive is provided by a motor 36 (Fig. 4) located on the base 12 at the rear of the casing 14 and connected, through a small pulley 38 and a belt 40, to a large pulley 42 pinned to a horizontal shaft 44 mounted in bearings in the frame of the machine, the shaft 44 extending from right to left or transversely of the machine as viewed in Fig. 1. The motor 36 drives the pulley 42 and shaft 44 continuously during the 60 operation of the machine, a ball bearing 46 being located between the right-hand bearing and the pulley 42 to decrease the friction and take the thrust of the moving parts. The continuously rotating pulley 42 has a vertical surface formed on its inner side and a friction clutch member 48, splined on the shaft 44, has a friction disk 47 adjacent to the pulley for engagement with said surface to cause rotation of the clutch when the members are forced together. A rear or hub portion of the clutch 48 is shaped in the form of a spool having a circumferential groove 49 formed therein, and the extreme inner end of the hub, as viewed in Figs. 1 and 4, has pinned to it a large driving gear 50. The inner side of the gear 50 has a surface formed thereon for en-

gagement with a friction-facing 51 secured to a fixed brake disk 52, in which is formed a bearing for the rotating shaft 44.

An arm 54, having an upwardly projecting yoke which straddles the spool-shaped portion of the 5 friction clutch 48, so that rolls 56 on the inner sides of the arms of the yoke will enter the circumferential groove 49 in the spool-shaped portion of the clutch, is fixed to the rear end of a rock shaft 58 rotatably mounted in bearings on the frame 10. An arm 60, fixed to the forward end of the rock shaft 58, extends toward the left (Fig. 1) and has a vertically disposed, cylindrical head 62 formed on its outer end. In the cylindrical head 62 is a vertical recess in which is mounted a plunger 64 having a stem which projects through an opening at the top of the head and has a collar 66 pinned on its upper end to retain the plunger in the recess. A compression spring 68, one end of which 20 bears against the top of the vertical recess and the other end against the enlarged body portion of the plunger 64, tends normally to force the plunger downwardly to its lowermost position as determined by the collar 66. The lower portion 25 of the plunger 64 is pivotally connected to the upper end of a toggle link 70, a lower link 72 of the toggle being pivotally secured to the frame 10 at 74. The toggle links 70, 72 are connected together by a pin 76 which projects for some 30 distance beyond the opposite sides of the toggle. A tension spring 61, connected at one end to the forward portion of the arm 60 and at the other end to the casing 14, tends to pull the arm 60 downwardly to rotate the shaft 58 so that the 35 arm 54 will hold the clutch 48 away from engagement with the pulley 42 when the toggle 70, 72 is broken.

A treadle 78 fixed on the forward end of a short, horizontal shaft 80, rotatably mounted 40 near the center of the machine in bearings 82 and 83 formed on the base 12, extends upwardly on an incline toward the right-hand side of the machine as seen in Fig. 1. The treadle 78 is held in its normally raised position by a torsion spring 45 84 surrounding a portion of the forward bearing 82 and having one end extending under the treadle and the other end hooked around a pin mounted in the bearing. On the rear end of the shaft 80, in front of the casing 14, is fixed an 50 upwardly extending arm 86 carrying on its upper end a roll 88 arranged to engage a downwardly projecting wedge-shaped portion 89 of a horizontal bar 90 mounted just above and in the same vertical plane as the arm 86. The right-hand or 55 forward end of the bar 90 as viewed in Fig. 1 projects downwardly and is bifurcated, each bifurcation having formed therein a substantially vertical slot 93. These slots receive the projecting ends of the pin 76 connecting the toggle links 60 70, 72, the weight of the bar 90 being supported by the pin which thus normally occupies the tops of the slots. The other end of the bar 90 is pivotally connected to a downwardly extending arm 92 of a three-armed lever fulcrumed at 94 on 65 the frame of the machine. This three-armed lever performs several functions simultaneously during the operation of the machine and for the present, only its utility in connection with the rotation of the turret 18 will be explained.

70 Mounted in bearings formed on a casing 96 projecting rearwardly from the column 16 and located a considerable distance above the horizontal shaft 44, is another horizontal shaft 98 parallel to the shaft 44. The greater portion of 75

the shaft 98 is inside the casing 96 but the right-hand end projects outside the casing and has pinned thereon a gear 100, equal in size to and meshing with the gear 50 on the shaft 44. Inside the casing 96 the shaft 100 carries a worm 102 which meshes with a worm wheel 104 secured to a vertical shaft 106 mounted in a bearing at the bottom of the casing and another bearing in a cover 108 which is bolted to the top of the casing. The shaft 106 is located behind and directly in line with the center of the turret table 18. Above the casing cover 108 the shaft 106 has mounted thereon a cam 110 and above the cam is mounted a horizontal arm 112 provided with a roll 114 the purpose of which will now be explained.

Each of the radial arms 30 which comprise the solid portions of the table 18 inside the shelf 33, has a rectangular projection or lug 116 formed 20 on its under side, the lug extending lengthwise of the arm so that it is positioned radially with respect to the circular table 18. A slot 118 is formed in each of the projecting lugs 116, these slots also extending lengthwise of the arms and 25 radially with respect to the table. The arm 112 which carries the roll 114 is of such length and so located that when the arm is at rest the roll 114 will occupy the inner end of one of the slots 118, thus positively holding the turret against 30 rotation.

When the treadle 78 is depressed, the shaft 80 is rocked to cause the roll 88 to contact with the wedge piece 89 on the bar 90, this contact taking place after a certain amount of lost motion, 35 indicated in Fig. 1 by a space between the roll 88 and the wedge 89. The bar 90 is then moved to the right (Fig. 1) to straighten the toggle links 70, 72 which rotates the arm 60 in a clockwise direction to cause the upper end of the yoke 54 40 to move the spool along the shaft 44 so that the driving gear 50 is moved away from the brake disk 51 and the friction disk of the clutch 48 is forced against the continuously rotating pulley 42 to rotate the gear 50. The movement of the 45 bar 90 is sufficient to move the toggle links past the point where the three pivots are in line and projections on the adjacent ends of the links contact with each other to maintain the toggle in straightened position, the spring 61 acting to hold 50 the toggle in such position. The spring and plunger construction on the end of the arm 60 provides a yield so that the toggle may be fully straightened after the clutch comes into engagement with the driving pulley 42. Rotation of the 55 gear 50 rotates the gear 100 and the shaft 98, thereby causing the worm 102, meshing with the worm gear 104, to rotate the vertical shaft 106 to actuate the arm 112. The mechanism described is constructed and arranged to move the 60 arm 112 through one revolution for each depression of the treadle 78, and the roll 114, at the end of one revolution of the arm 112, normally remains in the inner end of the slot 118 which has just been moved from the right to the left or 65 counterclockwise, as viewed in Figs. 3 and 5. When the roll is in the inner end of the slot 118 the arm 112 is positioned substantially at right angles to the slot, thus locking the table against 70 rotation while the operator is mounting and positioning a shoe and sole on the pad box at the operating station. Upon rotation of the arm 112 in a counterclockwise direction (Fig. 5), the roll 114 leaves the slot 118 in the left-hand lug and after an interval enters the slot in the right-hand lug to cause the turret table 18 and the sleeve 24

to be rotated with the arm 112, thus moving the turret one-sixth of a revolution to bring another pad box into the operating station. After the roll 114 leaves the slot 118 in the left-hand lug 5 116 the arm 112 travels through space for a part of its rotation before the roll enters the slot in the right-hand lug to cause rotation of the turret. This lost motion allows time for the pressure applying mechanism to operate before the turret starts to rotate, even if the treadle is fully depressed immediately as will hereinafter be more 10 fully explained.

As stated, the mechanism for turning the turret is constructed and arranged to make only one revolution for each depression of the treadle. 15 To accomplish this, even though the operator continues to hold the treadle down, there is provided a lever 120 (Fig. 5) extending forwardly and rearwardly of the machine and fulcrumed on a pin 122 mounted in an ear 121 projecting 20 from the side of the frame, the rear end of the lever 120 carrying a roll 124 which rides on the periphery of the cam disk 110 mounted on the vertical shaft 106. The cam disk 110 has a projection 111 at one portion of its periphery which 25 rises gradually from a concentric portion and then drops abruptly to join the concentric portion. The forward end of the lever 120 is pivotally connected by a pair of links 124, 126 to the upper end of an upwardly extending arm 30 128 of the three-armed lever which is pivoted at 94 to the frame of the machine. Upon rotation of the vertical shaft 106 to rotate the turret table one-sixth of a revolution as described, the cam 110 forces the rear arm of the lever 120 outwardly or to the left as viewed in Fig. 5 as the roll 124 rides up on the projection 111. The lever 120 is rocked about its pivot 122 so that its forward arm is moved to the right to swing the upper arm 128 of the three-armed lever inwardly. The three-armed lever is rotated about 35 its pivot 94 to pull back the horizontal bar 90 to break the toggle 70, 72, thus causing the clutch to be moved away from the continuously 40 rotating pulley 42 and the inner face of the gear 50 to be forced firmly against the brake disk 51. The gear 50 and mechanism driven thereby are thus brought quickly to a stop without any substantial overthrow of the moving parts due to 45 their momentum.

It will be seen, however, that before the bar 90 can be pulled back to break the toggle 70, 72, and move the clutch 48 away from the constantly rotating pulley 42, the wedge-shaped piece 89 must be lifted out of the path of the roll 88 50 on the arm 86. In order to move the wedge 89 out of the path of the roll 88, the bar 90 is provided with an upstanding portion 91 which is pivotally connected by a link 130 to the lower arm 60 of a bell-crank lever 132 fulcrumed on a pin 134 in the casing 14 and having a vertical arm 136 the upper end of which is pivotally connected to the forward end of a horizontal lever 138 (Fig. 4) pivotally mounted at 139 on a housing extending from the rear of the casing 14. The lever 138 extends forwardly from its pivot 139 and carries a roll 140 mounted between a pair of ears located somewhat behind the central portion of the lever.

A star-shaped cam 142 (Figs. 2 and 4) is 70 keyed to the reduced portion of the sleeve 26, inside the casing 14 in such a position that the roll 140 of the lever 138 will ride on its periphery. The cam 142 has six projections equally spaced around its periphery and the roll 140 passes over 75

one of these projections each time the turret 18 is rotated to move a pad box into the operating station. Consequently, each time the turret table is rotated one-sixth of a revolution, the 5 forward end of the lever 138 is swung to the left as viewed in Fig. 4 to rotate the bell-crank lever 132 about its pivot 134 and lift the horizontal bar 90 out of the path of the roll 88. The slots 93 in the forward end of the bar 90 permit 10 upward movement of the bar about its pivot 129 without disturbing the position of the toggle links 70, 72, which are holding the clutch 48 in driving engagement with the pulley 42. The bar 90 is now in an elevated position so that it may be 15 moved to the left, as viewed in Fig. 1, by the three-armed lever to break the toggle 70, 72 and release the clutch 48 without contacting with the roll 88 on the lever 86. The mechanism is timed so that the movement of the lower end of 20 the three-armed lever takes place after the bar 90 has been raised out of the path of the roll 88, a short dwell being provided on the outer ends of the star-shaped projections of the cam 142 for this purpose.

25 The pad box utilized in the illustrated machine comprises a hollow pad member 144 of heavy rubber the details of which are fully shown and described in applicant's co-pending application Ser. No. 621,231, filed on July 7, 1932. As 30 disclosed in the above-mentioned application, the hollow pad 144 is rectangular in plan view and has an upper surface which conforms substantially to the longitudinal contour of the bottom surface of a shoe, the pad being filled with a 35 conformable material such as sand so that it will conform more readily to the curvature of the shoe bottom. As also disclosed in the application mentioned above, the pad is divided into sections with spaces between, these spaces 146 40 and 148 (Fig. 8) being located respectively at those portions of the pad which separate the shank supporting portion from the forepart and from the heel end supporting portions of the pad.

45 The pad 144 is contained in a rectangular box-like confining member 150, arranged with one of its longer sides toward the operator and tangential to the path of rotation of the turret. Preferably the box is an aluminum casting, having a 50 horizontal shelf or plate 152 upon which the pad rests, the plate 152 being located slightly more than half way up from the bottom of the box. A plate 154, having a rounded end or rib 156, is positioned between the plate 152 and the 55 forward or forepart supporting portion of the pad, the rib 156 being located in a semicircular depression or groove 157 formed in the supporting plate 152. An upstanding projection or wall 158 is mounted on the plate 154 near its forward end, 60 the purpose of which will be later explained. Mounted on the supporting plate 152, outside the upstanding wall 158, is a member 160 having a vertical slot 161 formed in its lower portion one side of which has formed therein a series of 65 notches 162. The end of the plate 154 is reduced in size to form a handle 164 which extends through the slot 161 in the member 160 and through an opening 153 in the end of the pad box 150. When it is desired to vary the position 70 of the forepart of the pad 144, that is, the section resting on the plate 154 and in front of the space 146 (Fig. 8), to position this portion at the proper angle for the type of shoe being operated on, the handle 164 may be moved manually from one notch to another in the slot 161

to elevate or lower the plate 154. After the plate has been positioned the pressure of the pad 144 against the plate will hold the rib 156 in the groove 157, thus locking the plate in adjusted position. In order that the bottom surfaces of 5 the sections of the pad 144 may be maintained substantially in the same horizontal plane, a solid rubber pad 166 is inserted between the rear portion of the pad 144 and the plate 152 to compensate for the space occupied by the plate 154. 10

The sole and shoe must be located properly on the pad 144 before the sole attaching pressure is applied. Accordingly, the means for positioning the sole and shoe on the pad and the mechanism for actuating the sole and shoe positioning means 15 will now be described. Slidably mounted in ways formed by a pair of narrow plates 168, 170 (Fig. 9) secured by screws 172 to the upper edges of the heel end of the pad box 150 is a slide 174, the inner portion of which is cut away to allow space 20 for the heel ends of the sole and shoe on the pad 144. A rod 176, mounted horizontally in a pair of upstanding lugs 178 (one of which is shown in Fig. 9) formed on the upper surface of the slide 174, provides a pivot for a sole positioning member comprising a thin, pointed plate or tongue 180 secured to a cylindrical body portion 182. Extending downwardly from the under side of the pointed end of the tongue 180 is a small pin 184, the length of which is slightly less than the thickness of an outsole. The pin 184 is arranged 30 to enter a hole located in a predetermined position in the heel portion of an outsole to position the heel end of the outsole laterally of the pad. As shown in Fig. 8, the tongue 180 lies between 35 the outsole and the bottom of a shoe placed on the outsole so that the pin enters the hole from the upper side of the outsole. The slide 174 can be moved longitudinally of the pad box in the ways 168, 170 so that the operator may locate 40 soles of various sizes in the desired positions with respect to the forepart positioning means. When it is not in use the tongue 180 is held away from the pad by means of a leaf spring 186 secured to the slide 174 by a screw 188, the spring being 45 located to extend along the inner side of the lug 178 and under the cylindrical portion 182 of the tongue 180. A rectangular opening 190 is formed in the slide to provide space for the spring under the member 182. The free end of the spring is 50 bent to form an upwardly projecting tooth 192 and a projection formed on the cylindrical portion 182 of the positioning tongue 180, directly above the leaf spring 186, has an angular depression or notch 194 formed therein complementary in shape to the tooth 192 of the leaf spring. When the positioning tongue 180 is not in use it 55 may be lifted manually from the pad and the tooth 192 will snap into the notch 194 to hold the tongue away from the surface of the pad. When 60 the tongue is in operative position the end of the spring 186 bears against a flattened portion of the projection below the notch 194 to hold the plate firmly against the sole, thus keeping the pin 184 in the hole in the sole.

65 The means for positioning the forepart or toe end of the outsole comprises a thin sheet of rubber 196 approximately equal in width to the width of the pad box and positioned on the pad 144 so that it covers the forward portion thereof. The 70 rear edge of the rubber sheet 196 is beveled so that it will join the surface of the pad without forming a ridge. The sheet is stretched tightly over the upper surface of the pad and carries the positioning devices which locate the sole and shoe. 75

The under side of the rubber sheet 196 is reinforced with a layer of fabric material 197 which is vulcanized into the rubber and extends inwardly from opposite sides of the pad toward the center 5 of the sheet for a short distance beyond the positions occupied by the positioning devices. The fabric material prevents the rubber from stretching excessively at those portions of the sheet at which the positioning devices are located, there- 10 by causing the stretch to take place principally at the inner or central portion of the rubber sheet. When the means which holds the rubber sheet in its stretched condition is released the rubber contracts, causing the positioning devices to ad- 15 vance simultaneously toward the center of the pad to position the sole and shoe thereon. One margin of the rubber sheet 196 is clamped be- 20 tween a plate 198 and a metal clamping strip 200, and the other margin is clamped between a similar plate 202 and clamping strip 204, clamp- 25 ing screws 206 being used to hold the elements together. The plates 198, 202, which are located on the upper side of the sheet, extend inwardly from the outer edges of the pad, and are shaped 30 at their inner edges to conform substantially to the general outline of the sole of a shoe. The portions of the plates which are nearer the front end of the box project inwardly and have grooves 210, 212 formed in their upper surfaces, the 35 grooves being located centrally of the inwardly projecting portions and extending approximately at right angles to the inner edges of the plates. Similar projections are formed at the rear ends of the plates 198, 202, and grooves 214, 216 are 40 formed respectively in these projecting portions, these grooves also being located centrally of the projecting portions and extending substantially at right angles to the edges of the plates. In the forward groove 210 of the plate 198 is mounted 45 a sole positioning member or gage 218 and another sole positioning gage 219 is mounted in the forward groove 212 of the opposite plate 202. These sole positioning gages comprise a pair of thin plates (Fig. 11) which are bent at right an- 50 gles, the bent portions extending downwardly to- 55 ward the rubber sheet 196 and being divided into two separated prongs or blades which extend through the rubber sheet and, on the under side of the sheet, are again bent at right angles, there- 60 by preventing the gages from becoming separated from the rubber sheet. This arrangement makes it impossible for a sole to work under or be forced under the sole positioning gages during the sole locating operation and assures that the sole will 65 always be in contact with the sole engaging surfaces of the gages when it is being positioned on the pad. The reinforcing layer of fabric material 197 prevents excessive strain on the sole gages during the stretching and contracting action of the rubber sheet, since the sheet will stretch very little at the reinforced portions. The fabric ma- 70 terial also prevents the rubber from tearing or splitting at the openings where the sole gages go through the rubber sheet.

65 Adjustably mounted in the grooves 210, 212 respectively of the clamping plates 198, 202, on top of the sole positioning gages 218, 219, are a pair of shoe positioning members or gages 220, 222. A clamping screw 224 secures the gages 218, 220 to the plate 198, the screw extending through a slot 221 in the shoe gage 220 and a hole in the sole gage 218 so that the shoe gage may be ad- 75 justed in the groove 210 relatively to the sole gage. Another screw 226 secures the gage members 219, 222 in the grooves 212 of the clamping plate 202,

and a slot 223 in this shoe gage permits its adjustment relatively to the sole gage 219 so that the edge of the sole can be properly located relatively to the shoe upper. The shoe gages 220, 222, which are adapted to engage the forepart of the 5 shoe near the ends of the tip line comprise thin plates bent upwardly at their inner ends at right angles to the portions located in the grooves. Secured respectively to the vertical bent-up portions of the gages 220, 222 are small plates 225 10 (Fig. 11) the upper and lower ends of which extend somewhat beyond the bent portions of the gages. These plates form the shoe engaging elements of the gages and their lower ends extend downwardly toward the rubber sheet so as to 15 overlap the sole engaging portions of the sole gages which are located below and behind the plates. This arrangement insures that the shoe gages will always contact with the widest portion 20 of the shoe upper at the tip line even when the widest portions of the shoes are comparatively close to the surface of the pad.

The rear forepart positioning gages, which are arranged to engage the sole and shoe approxi- 25 mately at the ends of the ball line of the shoe, are similar in construction and operation to the positioning members which engage the sole and shoe at the tip line. A lower or sole positioning gage 228 is mounted in the groove 214 at the rear 30 end of the plate 198 and, adjustably mounted on the sole gage is a shoe positioning gage 230 se- 35 cured in the groove by a clamping screw 232. In the rear groove 216 of the clamping plate 202 there is likewise mounted a sole positioning gage 234 extending through the rubber sheet 196 in the manner described and above it is adjustably mounted a shoe positioning gage 236, the gages being clamped on the plate by a screw 238. The shoe positioning gages 230, 236, however, do not 40 have plates secured to the inner sides of their upstanding surfaces for insuring contact with the widest portion of the shoe at the ball line will ordinarily be high enough from the pad to contact with the 45 bent up surfaces of the gages.

Mounted respectively on the forward ends of the clamping plates 198, 202 and secured thereon by two of the clamping screws 206 of each plate, are a pair of inwardly projecting, horizontal arms 240, 242, the inner ends of which extend forwardly 50 toward the front end of the pad box. The edges of these inner ends are substantially parallel to the front end of the pad box, are slightly convex in shape, and are provided with a series of small teeth 244. The perpendicular plate or wall 158 55 on the plate 154, previously mentioned, curves toward the rear of the shoe at its upper end and has a row of small teeth 159 formed along the top of its inner side which mesh with the teeth 244 on the ends of the arms 240, 242 whenever the 60 arms are forced into engagement with the plate 158, thereby locking the positioning gages against separation. A guard 244, screwed to the top of the plate or wall 158 by screws 246 and extending over the top of the plate and the ends of the horizontal arms 240, 242, prevents anything from 65 getting between the plate and the arms.

Projecting inwardly and slightly rearwardly from the metal clamping strip 200 (Fig. 10), which is located on the under side of the rubber sheet 196, is a thin plate 248 of sheet metal, cut out at its central portion. The plate 248 is located between the forwardly projecting portions of the sole positioning members 218, 220 70 so that it will not contact with the ends thereof 75

which extend under the rubber sheet 196. A similar plate 252 projects inwardly from the metal clamping strip 204 and these plates form additional means for locking the sole and shoe positioning gages in operative position after the sole attaching pressure is applied. When the sole and shoe are pressed forcibly against the pad in a manner hereinafter described, the pressure forces the rubber of the sheet 196 and of the 5 pad 144 against the plates 248, 252 to hold them in the positions they then occupy. Since the pressure is applied after the gages have positioned the sole and shoe on the pad, the plates act to lock the gages in proper position as long 10 15 as the shoe remains under pressure. If desired, the inner portions of the locking plates 248 and 252 may be perforated as illustrated at 250 and 254 respectively, the perforations causing the plates to be gripped even more firmly between 20 the pad and rubber sheet, thereby increasing the locking action of the plates.

At the outer edge of the metal clamping strip 200 is a rectangular lug 256 provided with a series of holes 258. The lug 256 is connected by 25 means of a hook 259 inserted in one of the holes 258 to the upper end of an angle lever 260 (Fig. 12) pivotally mounted on a pin 262 extending between downwardly projecting ears 264 formed on the under side of the shelf 33 of the turret 18. 30 The angle lever 260 extends horizontally from its pivot 262 a little beyond the lower edge of the pad box 150 and then projects upwardly at right angles to its horizontal portion and substantially parallel to the side of the pad box. 35 Another arm 266 of the angle lever 260 extends inwardly toward the center of the pad box and has a pair of teeth 268 formed on its inner extremity.

The other metal clamping strip 204 has a rectangular lug 270 provided with a series of holes 272 in one of which is inserted a hook 273 for connecting the strip 204 to the upper end of another angle lever 274 shaped similarly to the lever 260 and pivotally mounted on a pin 276 40 in ears 278 projecting from the under side of the shelf 33. An inwardly projecting arm 280 of the angle lever 274 has formed on its inner end a single tooth 282 which meshes with the pair of teeth 268 on the inwardly projecting arm 266 of the angle lever 260, thus interconnecting the levers 260, 274 so that the upper ends thereof move equally and oppositely. Projecting downwardly from the inwardly extending arm 280 of the angle lever 274 is a lug 284 45 and a lug 286 projects downwardly from the under side of the arm 266 of the opposite angle lever 260. A compression spring 288, interposed between the inner surfaces of the lugs 284, 286, and supported by a horizontal rod 290, extending 50 through openings in the lugs and secured in position by a pin in the lug 286, tends normally to force the lugs apart and to move the upper ends of the levers inwardly toward the pad box. The spring 288, together with the rubber sheet 55 196, acts to hold the sole and shoe positioning gages inwardly against the sole and shoe. Mounted on a stud in the lower end of the lug 286 is a roll 292 by means of which the upper ends of the angle levers are forced outwardly to 60 stretch the rubber sheet 196 and separate the positioning gages, as will hereinafter be explained. 65

Two downwardly projecting lugs 294, 296 (Figs. 2 and 8) are mounted on the lower side of the shelf 33 under that portion of the pad which 70 75 supports the heel end of a shoe and, pivotally

mounted on a pin 297 extending through ears on the lug 296, is another angle lever 298 similar in construction and operation to the angle lever 260. An inwardly projecting arm 299 of the lever 298 is provided with a pair of teeth 5 which mesh with a single tooth formed on the end of an inner arm 301 of another angle lever 300 pivotally mounted in the lug 294. The upper ends of the interconnected angle levers 298, 300 are urged inwardly toward the pad box by 10 a compression spring 302 supported by a rod 304 extending between downwardly projecting lugs 303, 305 formed respectively on the lower portions of the levers 298, 300, the downwardly projecting lug 303 of the lever 298 being provided 15 with a roll 306 similar to the roll 292 on the lever 260. The upper end of the lever 298 is cylindrical in shape and has a horizontal opening in which is mounted a shoe-gage 308 having a 20 stem portion adjustably secured in the opening by a set screw 310. The shoe-engaging portion of the shoe gage 308 comprises a narrow vertical plate 311 formed on the inner end of the stem and of such length that it will engage the shoe upper at the widest portion of the heel end of 25 the shoe. A similar stem 312 is adjustably mounted in the upper end of the angle lever 300, being held therein by a set screw 314. A vertical plate 313 is formed on the inner end of this stem for engaging the shoe upper when the gage 30 is moved into operative position. As stated, the gages 311, 313, are normally urged inwardly toward shoe-engaging position by the action of the compression spring 302.

As each pad box is moved into the operating 33 station at the front of the machine, the fore-part positioning gages and the positioning gages for the heel end of the shoe, must be moved away from engagement with the sole and shoe in order to permit removal of the shoe and to provide 40 space for the introduction of another sole and shoe. To this end there is provided a slide member 316 (Figs. 2 and 6) slidably mounted in horizontal ways 318 formed in the forward end of a bracket 320 bolted to the frame 10 and extending 45 forwardly toward the front of the machine. The forward end of the slide 316 projects upwardly and has formed thereon a segmental member 322 which forms an arc of a circle having a center coinciding with the vertical axis of the turret 18. The arcuate segmental member 322 is located substantially in the same horizontal plane as the rolls 292, 316 of the angle levers 260, 298 so that as the slide 316 is moved forwardly in a manner which will 50 presently be described, the member 322 will engage the rolls 292, 306 which are then being moved into the operating station by rotation of the turret. The rear end of the slide 316 has formed thereon a vertical projection or shoulder 55 324 and at the central portion of the shoulder is formed a horizontal opening in which is secured a hollow bushing 326 extending rearwardly from the shoulder and having an enlarged portion 328 bearing against the rear surface of 60 the shoulder.

Extending upwardly from the bracket 320 (Fig. 6) behind the slide member 316, is another bracket 330, having a horizontal opening 331 formed near its upper end which is in line with 70 the bushing 326 extending rearwardly from the slide 316. A slide 332 is mounted for reciprocative movement in the opening 331, the forward end of the slide carrying a vertical plate 334 which extends downwardly toward the bracket 75

326. A stud 336 is threaded horizontally into the front end of the slide 332 in such a position that it will extend forwardly into the hollow bushing 326. The stud may be adjusted in the 5 slide 332 and a lock collar 338 is threaded on the stud to lock it in adjusted position when the collar is brought against the vertical plate 334. The stud is rounded at its front end so that it will slide easily in the bushing 326 and a horizontal slot 340 is formed in its forward portion. A pin 342 in the bushing 326 extends through the slot 340 to limit the sliding movement of the stud in the bushing and form a 10 means of connecting the rear slide 332 to the forward slide 316. A compression spring 344, one end of which bears against the enlarged portion 328 of the bushing and the other end against the vertical plate 334, tends to force the slides away from each other, so that the pin 342 will 15 normally be positioned at the forward end of the slot 340.

Rotatably mounted between ears on the rear end of the slide 332 is a roll 346 which engages the periphery of a star-shaped cam 348 (Figs. 2 and 5) keyed to the lower end of the hub 20 of the turret table 18. The cam 348 has six equally spaced projections around its periphery similar in design to those on the star-shaped cam 142 previously mentioned. In order to keep the roll 346 20 against the periphery of the cam 348 there is provided a compression spring 350 to press the slide 332 rearwardly. The spring 350 is mounted on a horizontal rod 352 one end of which is pinned in the lower portion of the vertical plate 334 25 on the forward end of the slide 332 and the other end slidably mounted in an angular bracket 354 secured to the supporting surface of the bracket 320. The spring 350 tends constantly to force the slide 332 rearwardly to keep the roll 346 30 against the periphery of the cam 348. The projections on the cam are so located that when a pad box is at the operating station the roll 346 will be on the top of a projection, as shown in Fig. 5, with the slides 332 and 316 in their forward position so that the segmental or arcuate member 322 will be holding the rolls, 292, 306 35 forwardly. As the turret is rotated a sixth of a turn to bring another pad box into the operating station, the roll 346 rides from the top of one projection into a depression and on to the top of another projection. The slides 332 and 316 are thus forced rearwardly and forwardly again by the combined action of the sprng 350 and the cam 348. The arrangement and timing of 40 the mechanism is such that the arcuate member 322 is withdrawn from its forward position as a pad box leaves the operating station and is moved forwardly again to engage the rolls 292, 306 on the next pad box after the rolls have been 45 moved sufficiently close to the operating station to insure that the member 322 will contact with both rolls as it moves forwardly. As the rolls 292, 306 ride over the convex surface of the arcuate member 322, the member is forced forwardly to rotate both pairs of interconnected levers about their pivots, thereby swinging the upper ends of the levers outwardly to move the shoe and sole positioning gages away from engagement with the sole and shoe. Since the forward movement 50 of the arcuate pusher member 322 takes place while a pad box is being moved from a position just in advance of the operating station, the positioning gages will have been withdrawn from engagement with the sole and shoe by the time the pad box reaches the operating station,

thereby permitting the operator to remove the shoe from the pad.

As stated, the star-shaped cam 348 holds the pusher member 322 forwardly to keep the positioning gages withdrawn until after the clutch 5 48 has been set and until the turret rotating mechanism has begun to rotate the turret a sixth of a revolution. In order to permit the positioning gages to be brought into operative position to locate a sole and shoe on the pad at the 10 operating station before the clutch 48 is set and while the star-shaped cam 348 is holding the pusher member 322 forwardly, treadle mechanism is provided for moving the pusher member 322 rearwardly against the action of the compression spring 344. This mechanism comprises a horizontal rock shaft 358 mounted above the rear end of the slide 316 in a pair of brackets 356 located on the bracket 320 and extending upwardly on opposite sides of the slide member 316. An arm 360, pinned to the rock shaft 358 and extending upwardly and forwardly, is pivotally connected at its upper end to the upper end of a treadle-operated rod 362. The lower end of the rod 362 extends through an opening formed in 15 a rearwardly projecting portion 79 of the treadle 78 (Figs. 1 and 2) and has secured on its lower end a bifurcated member 364 in which is mounted a roll 366. Above the roll 366 the bifurcated member is provided with a horizontal surface 368. The treadle 78 has a pair of ears extending downwardly from the rearwardly projecting portions 79 and mounted between these ears are rolls 370, 371 which are located directly above the horizontal surface 368 so that when the rod 362 is in 20 an elevated position they will contact with the surface 368. An opening is formed in the frame 12 below the rod 362 and adjustably secured to one side of this opening is an annular cam piece 372 having a surface 374 formed thereon inclined 25 laterally with respect to the treadle and located in the path of movement of the roll 366. When the treadle 78 is depressed the rod 362 is lowered by engagement of the rolls 370, 371 with the surface 368 on the member 364 attached to the lower 30 end of the rod. Downward movement of the rod 362 swings the arm 360 downwardly to rotate the rock shaft 358 in its bearings in the brackets 356. 35 As the treadle 78 nears the end of its downward movement the roll 374 on the lower end of the rod 362 contacts with the inclined surface 374 of the cam piece 372 so that the rod is deflected laterally to move the upper surface 368 of the bifurcated member 364 out from under the rolls 370, 371. The rod 362 is normally held in vertical position by a leaf spring 376 secured to and extending forwardly from a boss on the side of the frame. The forward end of the spring is looped loosely around the rod 362 and as the rod is deflected by the cam surface 374 the spring 40 bends with it. When the surface 368 clears the rolls 370, 371 the rod is elevated by a compression spring 378 surrounding the rod 362 and bearing at its upper end against a collar 380 pinned to the rod and at its lower end against the looped 45 end of the leaf spring 376. The leaf spring 376 returns the rod to vertical position and carries the roll 366 against an inclined surface 382 formed on the rear portion 79 of the treadle 78, this surface acting to move the roll 366 toward 50 the left (Fig. 2) as the treadle returns to its elevated position thereby causing the bifurcated member 364 to ride past the rolls 370, 371 until it is again forced under the rolls by the action of the leaf spring 376. The vertical projection 324 55

on the rear end of the slide 316 (Fig. 6) extends upwardly behind the rock shaft 358 and a cam disk 384, pinned to the shaft 358, has a downwardly projecting, eccentric portion 386 adapted 5 to be moved against the adjacent surface of the shoulder 324 when the rock shaft 358 is rotated in a counterclockwise direction by movement of the treadle-operated rod 362 downwardly. This forces the slide 316 rearwardly against the compression spring 344, the slot 340 in the stud 336 being long enough to permit the pin 342 to travel with the bushing 326 without contacting with the rear end of the slot. As the arcuate pusher member 322 on the slide 316 is moved rearwardly, the 10 spring 302, and the spring 288, if used, assisted by the rubber sheet 196, force the upper ends of the two pairs of interconnected angle levers inwardly toward the center of the pad 144, thereby carrying the sole positioning gages inwardly 15 20 against the edges of the sole and moving the heel gages inwardly toward the center of the pad. The location and action of the angle levers 260, 274 which control the stretching of the rubber sheet 196 is such that when the upper ends of the levers are swung outwardly by engagement of the roll 292 with the arcuate member 322, the stretch 25 of the rubber is greater at that part of the sheet which lies under the ball portion of the shoe than at the portion near the front end of the pad. This causes the horizontal arms 240, 242 which are arranged to mesh with the toothed plate 158 at the front end of the pad box, to be drawn away from the plate 158. Conversely, when the levers swing inwardly to bring the gages against the sole the contracting action of the rubber sheet causes the inner ends of the arms 240, 242 to be moved forwardly into close proximity to the toothed plate 158. When the sole gages contact with the edge of the sole they stop, the contracting 30 force of the rubber sheet and the strength of the spring 288, if used, being together only sufficient to cause the gages to be pressed firmly against the edge faces of the sole without causing it to buckle. If desired, the spring 288 may be dispensed with altogether and reliance may be placed on the rubber sheet for actuating the gages. Since the forepart gages are mounted on the rubber sheet 196 and are moved into operative position by the contraction of the rubber 35 sheet, they will, of course, be yieldable to a certain degree. The arrangement of the means by which the rubber sheet is stretched and is allowed to contract, namely, the pivotal connections formed by the hooks 259, 273 which connect the clamping strips 200, 204 respectively to the upper 40 ends of the angle levers 260, 274, permits a certain amount of lateral movement between the positioning gages which contact with the sole at the ends of the tip line and those which engage the sole near the ball line. Consequently, the forepart gages are capable of limited lateral movement relatively to one another and will thus, without adjustment, accommodate themselves to various shapes of outsoles. The timing of the machine is such that the treadle-operated rod 362 will not be cammed from under the rolls 370, 371 and returned to its elevated position until after the clutch 48 has been set to operate the turret rotating mechanism, thus preventing the 45 pusher member 322 from moving forwardly to withdraw the positioning gages from the sole and shoe before the sole attaching pressure has been applied.

After the sole has been placed on the pad and 50 the positioning gages at the toe end of the pad

have been moved into engagement with the forepart of the sole in the manner described, the shoe to which the sole is to be attached may be introduced between the shoe engaging surfaces of the shoe gages. The gages 308, 312 for the heel end 5 of the shoe are arranged to reach shoe engaging position a little later than the forepart positioning gages. This permits the operator to introduce the shoe between the forepart positioning gages and to lower the heel end of the shoe 10 against the sole before the heel gages contact with the heel portion of the shoe. When the heel gages contact with the heel end of the shoe they move it into a proper lateral position relatively to the sole which, as stated, is positively 15 held in position at the heel end by the pin 184 projecting from the tongue 180.

After the shoe and sole have been located properly with respect to each other on the pad at the operating station, they must be pressed forcibly 20 together in order to cause the sole to become permanently attached to the shoe. Accordingly, the mechanism in the illustrated machine for applying the sole attaching pressure will now 25 be described.

A hollow, flexible bladder or bag 388 (Fig. 8) composed of rubber or other yieldable material, for example, a portion of an inner tube for an automobile tire, is clamped to the under side of the horizontal plate 152 of each pad box 150. 30 The clamping means comprises a pair of clamping bars 390, 392 which extend transversely of the pad box and clamp the front and rear ends of the rubber bag respectively to the supporting plate 152, the bars being held in clamping position by 35 bolts 394. The hollow portion of the bag 388 between the clamping bars 390, 392, is adapted to be inflated with a fluid or liquid, for example water, and by such inflation to cause a downward pressure to be exerted against the shoe and 40 sole. The upper surface of the bag 388 is held closely in contact with the plate 152 by the clamping bars 390, 392 and the sides of the bag are prevented from distending beyond a limited amount 45 by engagement with the sides of the confining member or pad box 150. The opposite ends of the rubber bag are confined between a pair of vertical guides 414, 416, extending downwardly from the inner sides of the clamping bars 390, 392 so that when the bag is inflated the lower side is the 50 only portion thereof that is substantially distended. Liquid is admitted to inflate the rubber bag through an opening 396 formed in the upper side of the bag. An opening 398, registering with the opening 396 in the rubber bag, is formed 55 in the supporting plate 152 and through these openings is inserted a vertical nozzle 400 of a casting 402 which rests on the supporting plate 152 and extends under the pad 144. The casting 402 is provided with a horizontal passage 404 60 which communicates with an axial passage 406 in the vertical nozzle 400. The other end of the casting 402 extends beyond the inner side of the pad box 150 and is provided with an opening into which is threaded the forward end of a pipe 65 408 (Fig. 3) through which liquid is admitted and expelled from the rubber bag 388. The lower end of the nozzle 400 extending inside the bag is threaded to receive a nut 410 which clamps the casting 402 and the upper side of the bag tightly 70 against the supporting plate 152, a fiber washer 412 being mounted between the nut 410 and the bag to make the connection water tight.

As stated, the vertical guides 414, 416, which 75 form the confining means for the opposite ends

of the rubber bag 388, project downwardly from the inner sides of the clamping bars 390, 392 respectively. The guides are slotted at their lower edges and in these slots is located a plate-like member or plunger 418 which is arranged for vertical reciprocative movement below the rubber bag, the guides acting to prevent endwise or longitudinal movement of the plunger 418. The plunger is provided with a horizontal upper surface 420 which is normally held in engagement with the lower side of the bag and extends between the inner sides of the vertical guides 414, 416. The plunger 418 is preferably composed of comparatively light metal, such as aluminum, and the opposite ends thereof extend through vertical slots 422, 424, formed respectively in the toe and heel ends of the pad box 150 below the supporting plate 152. The slots extend to the bottom of the pad box and, together with the slots in the vertical guides 414, 416, determine the lateral position of the plunger 418 relatively to the pad box 150. The plunger 418 is maintained in its uppermost position with its horizontal upper surface 420 contacting with a portion of the lower side of the bag 388 by means of a pair of grasshopper springs 426, 428 mounted respectively on studs 430, 432 located under the horizontal surface 420 near opposite ends of the plunger. The upper arms of the springs bear against the under side of the surface 420 of the plunger and the lower arms, which are slightly curved at their lower extremities to facilitate the action of the springs, bear against the shelf portion 33 of the turret 18. The springs are strong enough to support the plunger and parts mounted thereon and to hold the upper surface 420 of the plunger lightly against the lower side of the rubber bag. When downward pressure is exerted against the plunger, however, the springs will yield to permit it to descend. The ends of the plunger which extend through the slots 422, 424, in the opposite ends of the pad box are provided with upwardly projecting ears between which is pivotally mounted a yoke or bail 434 which projects upwardly from the ends of the plunger and extends over the pad box longitudinally of the pad 144.

A slotted plate 436, adjustably mounted on the bail 434 over the forepart supporting portion of the pad and held thereon by screws, has a threaded cylindrical portion 438 projecting downwardly from the underside of its forward end. The cylindrical portion 438 has a vertical bore which receives the stem 439 of an adjustable toe rest 440, the lower portion of which has a conical surface 442 engaged by a leaf spring 444. The leaf spring 444 is riveted to a knurled hand nut 446, threaded on the cylindrical portion 438 below the plate 436, and the nut 446 may be screwed up or down to adjust the toe rest vertically. The shoe engaging portion of the toe rest comprises a slide member 448 having a T-shaped slot and being mounted on a horizontal plate 450 secured to the lower end of the stem 439. The lower or shoe engaging surface of the slide member 448 is covered with a piece of felt which is held in position by a strip of leather secured to the sides of the slide member by screws. This prevents the toe rest from scarring the shoe upper when it is pressed against the shoe during the pressure-applying operation.

At that part of the bail 434 which extends over the heel portion of the pad 144 is formed a projection 452 having an inclined lower edge which extends downwardly toward the central portion

of the pad and is provided with teeth 454. Inclined guideways are formed on the opposite sides of the projection 452 and slidably mounted in these guide-ways is a heel engaging member 456 (Fig. 8) for engaging the cone of a last B in a shoe 5 A mounted on the pad 144. The heel or cone engaging member 456 has a slot formed therein the bottom of which is inclined at the same angle as the lower edge of the projection 452. The bottom of this slot is also provided with teeth which mesh with the teeth on the projection 452. The member 456 is normally urged against the projection 452 to hold the teeth in engagement by means of a compression spring 458 mounted in a recess in the upper portion of the member 456 and bearing against a surface formed on the upper part of the projection. When it is desired to adjust the heel engaging member for different sizes of shoes, it may be pulled downwardly against the spring 458 to release the teeth and moved 10 along the projection until the desired position is reached. The spring 458 then forces the teeth into engagement to hold the member 456 in its adjusted position on the projection 452.

As stated, the bail 434 is pivotally mounted on 25 ears which project upwardly from opposite ends of the plunger 418 and is thus movable about an axis which is below the pad and extends beneath it. The pivotal movement of the bail is from a vertical or operative position over the pad 144 to 30 a rearwardly inclined position which removes the bail and shoe engaging devices 440, 456 from over the pad to a position where they are not over the pad and provides space for the operator to position a sole and shoe thereon. A pin 460, 35 mounted on the bail at the heel end of the pad box, extends into an arcuate slot 462 (Fig. 2) formed in the end of the pad box to limit the pivotal movement of the bail 434. At its outer end the slot 462 extends downwardly in a vertical direction to guide the bail 434 in its vertical downward movement in response to fluid pressure exerted against the plunger 418.

In applying pressure to the sole and shoe the bail 434 is first moved into a vertical position by 45 treadle-operated means, which will be described, and is then moved downwardly by distention of the rubber bag 388. As the bag is inflated the lower side is distended against the surface 420 of the plunger 418 to force the plunger downwardly 50 against the supporting springs 426, 428, thus moving the bail 434 downwardly until the last and shoe engaging members carried thereby are brought into engagement respectively with the last and shoe. The plunger is guided longitudinally in its 55 downward movement by the vertical guides 414, 416 on the clamping bars 390, 392, and the slots 422, 424 in the ends of the pad box, as well as the slots in the vertical guide plates, prevent the plunger from getting out of position laterally. As 60 the pressure in the bag increases the bail is moved downwardly with greater force to apply greater pressure to the shoe and sole. While pressure is being applied to the sole and shoe, the clutch 48 is set and the turret rotating mechanism causes 65 the turret to rotate to carry the pad box away from the operating station.

The bail 434 is elevated from its rearwardly inclined, inoperative position to a vertical, shoe-engaging position by treadle-operated means 70 actuated by the treadle-controlled rod 362 previously mentioned. An upwardly and rearwardly projecting arm 464 of the bracket 356 has pivotally mounted on its further side, as viewed in Fig. 6, a forwardly extending lever 466, the for- 75

ward end of which is enlarged and has a flat upper surface for engagement successively with the lower ends of a series of spring plungers 468 (Fig. 2) vertically mounted in bosses 470 projecting upwardly from the turret 18 and located near the inner corners of the front ends of the pad boxes 150. Each plunger 468 is made up of two parts, an upper portion having an enlarged head resting normally against the upper edge of the boss 470 and bored vertically to receive a lower portion which is held in the upper part by a slot-and-pin connection. A compression spring 472, one end of which bears against the top of the bore in the upper element of the plunger and the lower end against the inner end of a vertical bore formed in the lower element, keeps the two elements separated so that the plunger is normally extended to its greatest length. An inwardly extending arm 474, integral with the lower end of the bail 434 at the toe end of the pad box, has mounted on its inner end a roll 476 which contacts with the enlarged head of the plunger 468 when the bail is in its rearwardly inclined or inoperative position. A cam disk 478, having an eccentric portion 480, (Fig. 6) is pinned to the end of the rock shaft 358 in such a position that the periphery of the cam comes under the lower edge of the forwardly extending lever 466. When the rock shaft 358 is rotated by downward movement of the treadle-operated rod 362, the eccentric portion 480 of the cam disk 478 will rotate the lever 466 about its pivot so that the outer end of the lever, after moving through a space between it and the plunger 468, during which time the positioning gages are operated, will engage the plunger and force it upwardly. Upward movement of the plunger 468 forces the end of the arm 474 upwardly to swing the bail 434 into a vertical position over the pad. When the pin 460 in the bail 434 contacts with the forward end of the arcuate slot 462 in the pad box, the bail is prevented from further swinging movement, the compression spring in the plunger providing a yield for any further upward movement of the lever 466. Before this treadle-operated mechanism is released by deflection of the rod 362 by the cam surface 374, as previously described, the bail 434 has been caused to descend and apply pressure to the shoe and sole and will, therefore, be maintained in vertical, pressure-applying position until the liquid is expelled from the rubber bag 388, after which the bail is returned to elevated position.

The rubber bag 388 is expanded to apply pressure to the sole and shoe by means of liquid which is forced into the bag under pressure by a pump 482 (Fig. 2). The pump is clamped on the lower end of the vertical sleeve 24 and rotates with said sleeve. An intake pipe 484 extends downwardly from the pump into a supply tank 486 located in the base of the machine and containing the liquid by which pressure is applied. The pump is thrown into operation by means of a friction disk clutch 488 keyed to a vertical sleeve 490 rotatably mounted on the hollow sleeve 24. On the lower end of the sleeve 490 is formed a gear 492 which meshes with a driving gear 494 for the pump 482. Loosely mounted on the sleeve 490, above the gear 492, is a worm gear 496 meshing with a worm 498 formed on the horizontal shaft 44 which is continuously driven when the motor 36 is running, the worm 498 constantly rotating the worm gear 496 about the sleeve 490. An inwardly extending arm 500 (Figs. 1 and 2) of the three-armed lever which is pivoted at 94, is con-

nected at its inner end through a compression spring arrangement 502 to the forward end of a horizontal lever 504 pivoted at 506 to a lug 507 projecting downwardly from the upper portion of the casing 14, the lever 504 having an inner arm 509 (Fig. 4) in the form of a yoke which is provided with a pair of rolls 508 adapted to enter a circumferential groove 511 formed horizontally in the hub portion of the clutch member 488. The compression spring arrangement 502 between the levers 500 and 504 comprises a pair of oppositely positioned wire hooks extending through the ends of the levers and being surrounded at their central portions by a compression spring so that a yield is provided between the ends of the levers. The mechanism just described is operated in the following manner:

As the treadle 18 is depressed and begins to straighten the toggle links 70, 72, to move the friction clutch 48 into engagement with the constantly rotating pulley 42, the bar 90, which is pivotally connected at 129 to the lower arm 92 of the three armed lever, rotates this lever about its pivot 94 to move the inwardly extending arm 500 upwardly. The horizontal lever 504 is thereupon rotated about its pivot 506 in a clockwise direction, as viewed in Fig. 2, to force the clutch 488 downwardly into engagement with the upper surface of the worm gear 496 which is constantly rotated by the worm 498. When the clutch 488 is thus forced against the rotating worm gear 496, the sleeve 490 is rotated to drive the gear 494 which operates the pump 482. A ball-bearing 510, mounted on the sleeve 24 above the split housing by which the pump is clamped to the sleeve 24, forms a support for the sleeve 490 which carries the clutch 488 and worm gear 496. The ball bearing 510 takes the thrust of the parts when the clutch 488 is forced into operative engagement with the worm gear 496.

As stated, the pump 482 is clamped to, and rotated with, the vertical sleeve 24 so that whenever the turret 18 is rotated the pump moves with it, the supply tank 486 being large enough to permit the intake pipe 484 to travel in a circular path around the tank. This arrangement permits the pump to be operated while the turret table is rotating and to supply fluid under pressure to actuate the pressure applying units or plungers in any position of the turret table without having water tight joints between the source of pressure supply and the points of its application, for example, between the movable turret and its supporting column, as is usual in machines of this type. In the present construction it is practically impossible for leakage to occur between the pump and the pressure applying devices since no rotary joints are needed to connect the pump 482 with the fluid operated plungers on the rotating turret 18.

Since the friction clutch 488 is actuated by the arm 500 of the three armed lever which also controls the operation of the clutch 48 for rotating the turret 18, it will be seen that when the bar 90 is returned to inoperative position through the operation of the cam 110 and mechanism cooperating therewith as described, the forward end of the arm 500 is lowered to rotate the horizontal lever 504 and raise the clutch 488 away from its engagement with the constantly rotating worm gear 496 so that operation of the pump will cease each time the turret table comes to a stop. As stated, the pump will start to operate before the clutch 48 is set to actuate the turret rotating mechanism and before the treadle-controlled rod 75

362 is deflected by the cam surface 374. Consequently, liquid will be pumped into the rubber bag 388 to lower the ball into engagement with the shoe before the rod 362 returns the ball swinging mechanism to inoperative position. If the operator desires to apply the full pressure to the shoe before the turret starts to rotate he may do so by holding the treadle depressed part way to actuate the pump but not far enough to set the clutch 48. In this way he will cause fluid to be forced into a rubber bag 388 to actuate the plunger 418 without causing the turret rotating mechanism to be actuated.

Since the pressure applied to the shoes and soles is determined by the pressure in the rubber bags 388, the illustrated machine is provided with means whereby the pressure in the bags may be regulated and controlled so that only a predetermined pressure will be applied to the shoe and sole. The mechanism for supplying liquid under pressure to the rubber bags 388 and for controlling the pressure of the liquid will now be described. When the pump 482 starts operating, liquid, for example water, is drawn from the supply tank 486, through the intake pipe 484, into the pump 482 and is then forced through a pipe 512 connecting the pump to the lower end of a vertical inlet pipe 514 (Figs. 2 and 7) which extends upwardly through the hollow sleeve 24 and at its upper end is threaded into the lower portion of a circular casting 516, resting in a depression 517 formed at the center of the turret table 18. The circular casting 516 forms the pressure controlling unit from which liquid under a predetermined pressure may be supplied to the rubber bags. The upper end of the inlet pipe 514 connects with a vertical opening 518 in the casting 516 which communicates with a circular pressure chamber 520 formed in the upper portion of the casting.

A ball check valve 522 is located at the top of the passage 518 which communicates with the pressure chamber 520 and when the valve 522 is seated no water can leave the chamber. A light compression spring 524 bears against the top side of the ball valve 522 and normally holds it against its seat in the opening 518, the upper end of the spring bearing against the top of a circular recess 526 formed in the lower portion of a pressure gage 528 threaded into a boss on the upper wall of the chamber 520 above the inlet pipe 514. As liquid is pumped through the inlet pipe 514 into the chamber 520, the check valve 522 is forced away from its seat by the pressure of the liquid, so that as long as the pump is operating, liquid is passing into the pressure chamber 520.

Located at equal distances from each other around the vertical side wall of the chamber 520 are six horizontal openings or passages 530 which extend radially from the chamber 520 and form the means by which liquid is admitted to the six rubber bags 388 of the pad boxes 150. These passages 530 communicate with a circular chamber 532 formed near the outer edge of the casting 516. Another check valve 534, similar in construction to the valve 522, is provided at the outer end of each of the passages 530, the valves 534 being normally held against their seats by light compression springs 536. The circular chamber 532 is connected by short, vertical passages 544, formed at the bottom of the chamber, with six horizontal passages 546, located directly below the passages 530 and extending radially through the outer wall of the casting 516.

At its inner end each of the passages 546 opens into another circular chamber 548 located below and having substantially the same outside dimensions as the pressure chamber 520. Unlike the chamber 520, however, the chamber 548 is not one continuous opening but is formed as a circular passage which extends around an inner portion of the casting 516. The outer wall of this portion of the casting 516 forms the inner wall of the circular chamber 548 and is positioned considerably nearer the outer wall of the circular passage 548 at one side of the passage than at the other. The outer ends of the passages 546 which lead from the circular chamber 548 are connected to the inner ends of pipes 549, which in turn are connected by unions 550 to the pipes 408 that communicate with the rubber bags 388 in the pad boxes 150. It will be seen from the above that the rubber bag of each of the pad boxes on the turret table 18 is supplied with liquid from the pressure chamber 520 by means of a separate set of passages leading from the pressure chamber 520.

Liquid is admitted to and expelled from each rubber bag through the single conduit or pipe 408, 549 which connects each bag with the pressure controlling unit 516 and it is therefore necessary to control the passages through which the liquid passes in such a manner that the liquid will be forced into the bag under pressure, be retained under pressure during the pressing operation, and be expelled from the bag only after the pressing operation has been performed. To this end there is provided for each set of passages a two-position taper valve or cock 552, rotatably mounted in a suitably shaped opening formed in a solid portion of the casting 516 between the pressure chamber 520 and the outer chamber 532 and extending across the passages 530 and 546. The taper valve 552 is provided with two horizontal passages 554 and 556 which pass through the center of the valve and are equal in size to the passages 530 and 546. The passages 554 and 556 are located respectively in the same horizontal planes as the passages 530 and 546, the upper passage 554 being positioned at right angles to the lower passage 556. When the valve 552 is rotated in the casting 516 until the passage 554 registers with the passage 530, a continuous opening will be formed from the pressure chamber 520 to the circular chamber 532 and the lower passage 556 of the valve will be positioned so that the passage 546 will be closed. Conversely, when the valve 552 is rotated ninety degrees from the position just described, the upper passage 530 will be closed and the lower passage 546, leading to the chamber 548, will be opened. The lower portion of each taper valve 552 is reduced to form a shaft 558 which extends downwardly beyond the casting 516 through a circular opening 560 in the turret table 18. A compression spring 562 encircles the upper portion of the shaft 558, the lower end of the spring bearing against a collar 564, supported by a pin 566 extending through the shaft 558. The upper end of the spring 562 presses another collar 568 upwardly against a surface formed on the under side of the casting 516, thereby keeping the valve 552 seated in the casting 516 and creating enough friction between the valve and the casting to hold the valve in proper position until it is forcibly rotated into another position.

Pinned to the lower end of each of the shaft portions 558 of the valves 552 by a taper pin 75

570 is a collar 572 provided with four horizontal projections or lugs 574 extending radially from the lower portion thereof, the lugs being located ninety degrees apart around the collar so that it 5 will appear cross-shaped in plan view. These cross-shaped collars 572 provide means in conjunction with which other means cooperate to rotate the valves 552. Before describing the construction and operation of the means for rotating the valves, however, it will be proper at this point to complete the description of the pressure controlling unit in order to show how the desired pressure is secured and maintained in the rubber bags, and how the water is expelled from the 10 bags and returned to the supply tank 486 at the base of the machine.

As stated, liquid is pumped through the inlet pipe 514 into the pressure chamber 520 in the casting 516. The check valve 522 permits liquid 20 to enter the chamber so long as the pressure of the liquid in the inlet pipe 514 is sufficient to overcome the tension of the light spring 524. When the pump stops, the check valve 522 closes the inlet pipe 514 and prevents the liquid from 25 returning to the pump. While the machine is operating all of the valves 552 which control the admission of liquid into the rubber bags, except the valve for the pad box which is being moved into the operating station, are open, that 30 is, are in a position in which the upper passages 530 are open. The liquid passes from the chamber 520 through the upper passages 530 into the chamber 532. The check valves 534 which 35 cover the passages 530 prevent the liquid from returning to the pressure chamber after once it has entered the circular chamber 532. From the chamber 532 the liquid passes through the vertical openings 544 into the horizontal passages 546. Since the inner ends of these passages, leading 40 to the circular chamber 548 (which is the discharge chamber) are closed, the liquid must pass from the passages 546, through the pipes 549, 408, into the rubber bags 388. It will be seen that whatever pressure is created in the 45 pressure chamber 520 will also be created in each of the six rubber bags 388 the valves of which are open during the operation of the pump 482. Moreover, if the pressure should be lowered in any of these bags through leakage or otherwise, 50 the pressure is restored to the required amount each time the pump is operated.

The inlet passage 530, which controls the admission of liquid into the rubber bag 388 of the pad box that is being moved into the operating station, is closed, as will hereinafter be described, after the pad box has started to travel toward the operating station and, as the valve 552 is rotated to close this inlet passage, the lower or discharge passage 546 is opened. After the 55 discharge passage 546 has been opened the liquid in the rubber bag is permitted to flow out of the bag into the discharge chamber 548, thereby releasing the shoe and sole as the plunger 418 is elevated by the grasshopper springs 426, 428 to raise the bail 434 away from engagement with the last and shoe.

A discharge pipe 516 extends from the bottom of the chamber 548 downwardly through the hollow sleeve 24 into the supply tank 486, the upper end of the pipe being threaded into the lower wall of the casting 516 in the same manner as the inlet pipe 514. The liquid discharged from each rubber bag at the operating station is thus 70 returned from the discharge chamber 548 to the

supply tank at the base of the machine. A plug 578 is threaded into an opening at the bottom of the discharge chamber 548 to permit access to the chamber in case any of the passages become plugged up.

In order to insure that a predetermined pressure will be created in the pressure chamber 520 there is provided an adjustable pressure control valve constructed and arranged to retain the liquid in the chamber 520 until the pressure reaches a predetermined amount and then to operate automatically to exhaust the surplus into a relief chamber. The control valve comprises a stem 580 having an enlarged head 582 the upper portion of which is frusto-conical in shape and is normally held against a valve seat formed at the lower end of a circular passage 584 which connects the pressure chamber 520 to a relief chamber 586, formed in the inner portion of the casting 516 that is located within the circular discharge chamber 548. A part of the valve stem 580 is threaded and above the threaded portion the stem is reduced in size and enters a vertical bore formed in the lower portion of a valve adjusting member 588. An adjusting nut 590 is mounted on the threaded portion of the valve stem 580, this nut having two slots 592 which are diametrically opposite and into which enter two downwardly projecting pins 594 formed on the lower end of the valve adjusting member 588. Interposed between the nut 590 and a washer 596 encircling the valve stem 580 and resting against the bottom side of the pressure chamber 520, is a compression spring 598 which urges the valve upwardly to keep the conical portion pressed firmly against the valve seat at the lower end of the opening 584. The washer 596 is provided with a series of holes to permit liquid to pass from the pressure chamber into the relief chamber when the pressure control valve is open. The valve adjusting member 588 is rotatably mounted in a holder 600 threaded into a large opening formed in the casting 516 at the top of the pressure chamber 520, the upper portion of the holder being reduced in size and threaded to receive a confining nut 602. A part of the holder 600 which surrounds the adjusting member 588 is cut away and in the opening thus formed is inserted a piece of packing to prevent leakage from the chamber 520, the packing being held in position by the confining nut 602. Pinned to the upper end of the adjusting member 588 is a handle 604 and a spring 606, interposed between the handle and the confining nut 602, holds the adjusting member 588 in its uppermost position with the enlarged portion at its lower end bearing against the top of a recess 608 in the lower end of the holder 600.

When it is desired to increase the pressure of the liquid in the pressure chamber 520 the operator turns the handle 604 to lower the adjusting nut 590 and increase the tension of the compression spring 598, thereby causing the spring to press the valve more firmly against its seat at the lower end of the passage 584. When the pressure in the chamber becomes sufficient to overcome the force of the spring 598, the pressure control valve opens to permit the liquid to exhaust into the relief chamber 586. A pipe 610, 70 the upper end of which connects with a curved passage 612 opening into the relief chamber 586, extends downwardly through the hollow sleeve 24 and provides means whereby the liquid expelled from the pressure chamber 520 may be returned 75

to the supply tank 486 at the base of the machine. It has already been pointed out that a pressure gage 528 is mounted above the chamber 520 to indicate what pressure is being created therein. 5 Since the pressure in the chamber 520 is substantially the same as that in the several rubber bags 388, the operator can tell from the gage whether the pressure in the bags is too high or too low and can adjust the pressure control valve accordingly.

The means for rotating the valves 552 which control the admission of liquid to the rubber bags comprises a pair of upwardly projecting fingers for engaging the cross-shaped members 572 which are pinned to the lower ends of the valves. One of these valve operating fingers 614 (Fig. 5) is fixed and engages an arm 574 of the cross-shaped member 572 as a pad box is being moved from the sixth station to the operating station. The other valve operating finger 620 is movable and is operated by treadle-controlled mechanism which will presently be described. The fixed finger 614 extends upwardly from the outer end of an arm 616 projecting laterally from the rear portion of a bracket 618 bolted to the upper end of the bracket 330 aforementioned. The finger 614 is so positioned that, as the turret is rotated to bring a pad box into the operating station, the finger will contact with a forwardly projecting arm 574 of the cross-shaped member 572 which is mounted on the valve 552 associated with this pad box to rotate the valve ninety degrees as the pad box is moved into the operating station. Rotation of the valve 552 closes the inlet passage 530 which, as stated, is open from the time the pad box leaves the operating station until it reaches the position now being described, and opens the lower or discharge passage 546, thus permitting the liquid in the rubber bag 388 to pass into the discharge chamber 548 and through the outlet pipe 576 into the supply tank 486. As the rubber bag contracts the plunger 418 rises to lift the shoe engaging members of the bail 434 away from the last and shoe.

45 After another shoe and sole have been positioned on the pad and before the turret table starts rotating, the valve 552 must be again rotated ninety degrees to close the outlet passage 546 and open the inlet passage 530 to allow liquid 50 to enter the rubber bag 388 and apply pressure to the shoe and sole before the pad box leaves the operating station. Rotation of the valve in this case is performed by the finger 620 (Fig. 6) 55 which is pivotally mounted on a lug 621 projecting upwardly from the rear end of a slide 622. The slide 622 is mounted in a T-shaped slot 624 extending longitudinally of the bracket 618 which is bolted to the top of the bracket 330. The forward end of the slide 622 is pivotally connected 60 to the rear end of a horizontal link 626 the forward end of which is pivotally connected to the upper end of an arm 628 pinned to the rock shaft 358. The finger 620 is so positioned that as the treadle 78 is depressed and the rock shaft 358 65 rotated, the slide 622 is moved forwardly to cause the finger 620 to engage an arm 574 of the cross-shaped member 572 to rotate the valve 552 ninety degrees, thereby closing the outlet passage 546 and opening the inlet passage 530 so that liquid will 70 flow from the pressure chamber 520 into the rubber bag mounted in the pad box which is then at the operating station.

The finger 620 is held in a vertical position 75 against a surface or stop 625 formed on the top

of the lug 621 by a leaf spring 623 secured to the slide by a screw 627 and pressing against the inner surface of the finger. When the finger is moved forwardly to rotate the valve 552 it is against the stop 625 and is therefore rigid. When 5 the treadle rod 362 is released by the cam surface 374 and the slide 622 is returned to normal position, the finger 620 can bend forwardly against the spring 623 as the finger contacts with another arm 574 of the valve at the operating station 10 which has now been rotated into its path. The finger is thus returned into position to engage a projection 574 on the valve of the next pad box 15 when it has been rotated into the operating station.

In the operation of the machine, the operator places an outsole on the pad 144 and locates its rear end by engaging the pin 184, projecting from the tongue 180, with the hole formed in the heel end of the outsole. He then depresses 20 the treadle 78 which lowers the treadle-controlled rod 362 to withdraw the arcuate pusher member 322 sufficiently to permit the rubber sheet 196 to contract to move the toe gages inwardly toward the sole. When the gages contact with the sole they stop since, as stated, the contractive force of the rubber sheet 196 is not sufficient to cause the gages to buckle the sole. The operator may now introduce the toe end of the shoe between the shoe gages which have been 25 adjusted to locate the shoe in the desired position relatively to the sole. In locating the shoe it may have to be pressed with some force against the forward or tip line gages in order to introduce the shoe between them. Such pressure, 30 however, will immediately force the locking arms 240, 242 against the toothed plate 158, thus locking the gages against separation. The heel gages, 35 which are constructed and arranged to come into engagement with the shoe a little later than the forepart gages, now locate the heel-end of the shoe laterally in the desired position with respect to the sole. The treadle 78 may be released if necessary to cause the gages to separate and allow readjustment of the sole or shoe.

45 As the operator depresses the treadle a little farther the bail 434, which may have been moved partly into an upright position during the sole and shoe positioning operation, is now swung upwardly into a vertical position over the shoe and sole. This movement of the treadle also causes the finger 620 to rotate the valve 552 ninety degrees to open the inlet passage 530 to the rubber bag 388. By further movement of the treadle 78 the bar 90 is moved toward the right (Fig. 1) 50 to rotate the three armed lever about its pivot 94 far enough to force the pump clutch 488 against the rotating worm gear 496, thus starting the pump 482. Liquid under pressure is forced into the pressure chamber 520 and from 55 the pressure chamber into the rubber bag 388. As the lower side of the bag is distended the plunger 418 descends to bring the last and shoe engaging members on the bail 434 into engagement with the last and shoe to force the shoe 60 and sole firmly against the pad 144.

If the operator discovers that the shoe and sole have for any reason been moved from their proper positions on the pad before the pressure has been fully applied he may release the treadle 70 at this point to stop the pump and prevent further pressure being applied, since the mechanism for rotating the turret has not yet been actuated and the machine is still under the operator's control. In order to reposition the shoe and sole, 75

however, he must release whatever pressure has already been applied. To do this he merely reaches under the turret and turns the valve 552 a quarter of a turn to close the inlet passage 530 and open the outlet passage 546, thus letting the liquid out of the rubber bag and permitting the grasshopper springs 426, 428 to raise the plunger 418 and lift the bail 434 away from the shoe. This arrangement enables the operator to control the operation of the pressure applying mechanism until he is certain that the shoe and sole are properly positioned on the pad before depressing the treadle completely to cause operation of the turret rotating mechanism.

In conjunction with the starting of the pump and a little later the toggle links 70, 72 are fully straightened to move the clutch 48 into operative engagement with the constantly rotating pulley 42, thus starting the shaft 98 and causing the turret rotating mechanism to begin operating. After the pump has started and pressure has been applied to the shoe to lock the gages in position by forcing the rubber of the sheet 196 and pad 144 into the holes formed in the inner ends of the plates 248, 252, the cam surface 374 cams the treadle-controlled rod 362 away from the rolls 370, 371 on the under side of the treadle and permits the spring 378 to return the rod to elevated position, thereby rotating the rock shaft 358 back to its normal position and returning the bail elevating mechanism and the valve operating finger 620 into inoperative positions. The clutch 48, which was set during the latter part of the downward movement of the treadle 18, shortly before the rod 362 was released, has actuated the turret rotating mechanism and the arm 112 has left the slot 118 on the left-hand side of the turret, moved through the space separating this slot from the slot at the right, and is now rotating the turret through a sixth of a revolution.

The arcuate pusher member 322, which was also moved rearwardly by actuation of the treadle-controlled rod 362, does not return to its forward position upon release of the rod 362 because the star-shaped cam 348, which controls the movements of the arcuate cam and which is rotated with the turret 18, has now been rotated sufficiently by the turret to cause the roll 346 to ride off the top of a projection and into a depression of the cam, thereby permitting the slides 332 and 316 and the arcuate member 322 to move still farther rearwardly in order to remove the arcuate cam from the path of the rolls 292, 306, 55 of the next pad box which is now being moved into the operating station. If the operator continues to hold the treadle down, the star-shaped cam 142 causes the lever 138 to rotate the bell-crank lever 132 about its pivot 134 to elevate the front end of the bar 90 and move the wedge-shaped projection 89 out of the path of the roll 88. The cam 110 forces the lever 120 to rotate the three-armed lever about its pivot 94 in a clockwise direction as viewed in Fig. 1 to return the bar 90, break the toggle 70, 72 and separate the clutch 48 from the constantly rotating pulley 42. The same movement of the three-armed lever lowers the arm 500 to raise the clutch 488 away from the rotating worm gear 496. Thus it will be seen that the turret 18 can make only one sixth of a revolution for each depression of the treadle whether or not the treadle is released by the operator. It will also be apparent that the pump is operated before the turret rotating mechanism starts operating and will con-

tinue to operate throughout the turning movement of the turret. The pump will, however, be thrown out of operation when the turret stops rotating. Consequently, even if the treadle is fully depressed immediately so that the clutch 48 is set and the turret rotating mechanism commences to operate at once, sufficient pressure will have been applied to the shoe to hold it in proper position on the pad before the turret actually begins to turn because of the lost motion of the roll 114 as it moves through space while passing from the slot 118 for the pad box at the left to the slot for the pad box at the right, as viewed in Fig. 5.

As another pad box approaches the operating station the projection 614 on the bracket 618 rotates the valve 552 a quarter of a revolution to close the inlet passage 530 and open the discharge passage 546. The liquid passes out of the rubber bag 388 into the chamber 548 and through the pipe 576 into the supply tank 486. This causes the bag to contract and the springs 426, 428 force the plate 418 upwardly to raise the bail 434 away from the shoe. The operator may then swing the bail into its inclined position and remove the shoe with the sole attached, the shoe and sole gages having been withdrawn by engagement of the rolls 292, 306 with the arcuate pusher member 322 which has been moving forwardly under the influence of the star-shaped cam 348 while the pad box was being rotated into the operating station. After the shoe and attached sole have been removed the operator may position another shoe and sole on the pad and repeat the operations which have been described.

Having described the invention, what I claim as new and desire to secure by Letters Patent of the United States is:

1. In a cement sole attaching machine, the combination of a rotatable turret, a plurality of pads on the turret, a plurality of shoe engaging devices each movable outwardly of the turret from a position where it is not over the pad into position over a shoe on the pad, and means for operating said devices in turn to press a shoe against a pad.

2. In a cement sole attaching machine, the combination of a rotatable turret, a plurality of upwardly facing pads on the turret, a plurality of shoe engaging devices movable bodily outwardly of the turret from a position where they are not over the pad into operative position over the respective pads, and means independent of movement of the turret for operating the said devices in turn to press a shoe against a pad.

3. In a machine for cement sole attaching, the combination of a plurality of pads, a carrier for presenting each pad in turn at an operating station with one of the longer sides of the pad adjacent to the operator, and shoe holding devices each movable from a position where it is not over the pad into position over a pad from that side of the pad which is remote from the operator.

4. In a machine for cement sole attaching, the combination of a turret arranged for rotation on a vertical axis, a plurality of sole receiving pads on the turret, and shoe engaging devices each pivoted on the turret and arranged to swing radially of the turret about an axis below the pad into and out of position over a shoe on one of the pads.

5. In a cement sole attaching machine, the combination of a rotatable turret, a plurality of pads on the turret arranged with their long axes

in the direction of rotation of the turret, a plurality of shoe engaging devices movable outwardly of the turret each into position over a shoe on one of the pads, and means for operating the shoe engaging devices in turn to press a shoe against a pad.

6. In a machine for cement sole attaching, the combination of a turret arranged for rotation on a vertical axis, a plurality of upwardly facing pads on the turret, a plurality of shoe engaging devices arranged each to swing about an axis parallel to the lengthwise dimension of the pads radially of the turret into and out of position over the pads, and means for causing relative movement of each pad and its corresponding shoe engaging device to apply pressure to a shoe and sole located on the pad.
- 10 15

7. In a machine for cement sole attaching, the combination of a turret arranged for rotation on a vertical axis, a plurality of sole pads on the turret, a plurality of shoe engaging devices mounted on the turret and each arranged to move radially of the turret into and out of position over a shoe on one of the pads about an axis below the pad, and means between each pad and said last named axis for causing relative movement of the pad and the corresponding shoe engaging device vertically to apply pressure to the shoe sole.
- 20 25

8. In a cement sole attaching machine, the combination of a rotatable turret, a plurality of upwardly facing pads on the turret, a plurality of shoe engaging devices movable outwardly of the turret into position over the pads, fluid-pressure-operated means for operating said devices in turn to press a shoe against a pad, and manually operated means for moving said shoe engaging devices in turn outwardly of the turret and for controlling the operation of said fluid-pressure-operated means.
- 30 35

9. In a machine for cement sole attaching, the combination of a plurality of upwardly facing pads, a carrier for presenting the pads in turn at an operating station with a side of the pad adjacent to the operator, a shoe engaging device for each pad movable into position over the pad at the operating station from that side of the pad which is remote from the operator, and expandible means between each pad and the carrier and operable when a shoe engaging device is over the pad for moving it vertically toward the pad.
- 40 45

10. A machine for use in the manufacture of shoes having, in combination, a pad for supporting a sole and shoe, a flexible vessel mounted below said pad, reciprocatory means for applying pressure to the sole and shoe, said means being in contact with said flexible vessel, and means for distending said vessel to actuate said reciprocatory means thereby causing pressure to be applied to the sole and shoe.
- 50 55

11. A machine for use in the manufacture of shoes having, in combination, a plurality of pads each arranged to receive a sole and shoe, means for presenting the pads successively at an operating station, reciprocatory means for applying pressure to the shoes and soles, means for actuating said reciprocatory means, said actuating means including a flexible member constructed and arranged to be distended to cause reciprocation of said reciprocatory means, and means for distending said flexible member.
- 60 65

12. A machine for use in the manufacture of shoes having, in combination, a pad arranged to receive a shoe and sole, a reciprocatory member for applying a predetermined pressure to the

shoe and sole, a flexible member comprising a hollow vessel adapted to be inflated to cause said reciprocatory member to apply said pressure, and means for admitting fluid under pressure to said flexible member to cause such inflation.

5

13. A machine for use in the manufacture of shoes having, in combination, a rotatable turret, a plurality of pads mounted on the turret and arranged each to receive a shoe and sole, means for applying pressure to the shoe and sole, a hollow, flexible vessel mounted below the pad and having a portion thereof in engagement with said pressure applying means, and means for admitting fluid under pressure to said vessel whereby it is inflated to cause the pressure applying means to be moved forcibly in one direction, thereby causing pressure to be applied to the shoe and sole.

15

14. In a cement sole attaching machine, the combination of a rotatable turret, a plurality of upwardly facing pads on the turret, a plurality of shoe engaging devices each movable outwardly of the turret and laterally of one of the pads into operative position over a shoe on the pad, and means independent of movement of the turret for operating said devices in turn each to press a shoe against a pad.

20

15. In a machine for cement sole attaching, the combination of a plurality of upwardly facing pads, a carrier for presenting the pads in turn at an operating station with one of the longer sides of the pad adjacent to the operator, a shoe engaging means for each pad movable into position over the pad at the operating station from that longer side of the shoe which is remote from the operator, and means operable when a shoe engaging device is over a pad for moving it vertically toward the pad.

30

16. In a cement sole attaching machine, the combination of a rotatable turret, a plurality of upwardly facing pads on the turret, a plurality of shoe engaging devices movable outwardly of the turret into cooperative relation to the corresponding pad, power-operated means independent of rotation of the turret for operating said devices in turn to press a shoe against the pad, and a single manually operated means for moving each shoe engaging device in turn outwardly of the turret into position over the corresponding pad and for causing operation of said power-operated means.

40

17. In a machine for cement sole attaching, the combination of a plurality of upwardly facing pads, a carrier for presenting the pads in turn at an operating station with a side of the pad adjacent to the operator, a shoe engaging means for each pad movable into position over the pad when the pad is at the operating station from that side of the pad which is remote from the operator, manually operated means for moving each shoe engaging device in turn into position over the pad, fluid-pressure operated means operable when a shoe engaging device is over the pad for moving it vertically toward the pad, and connections to said manual means for causing operation of said fluid-operated means.

50

18. In a machine for cement sole attaching, the combination of a plurality of upwardly facing pads, a carrier for presenting the pads in turn at an operating station with one of the longer sides of a pad adjacent to the operator, a shoe engaging device for each of the pads movable into position over its pad from that longer side of the shoe which is more remote from the

60

65

70

75

- operator, and power-operated means for moving the shoe engaging means toward the pad.
19. In a cement sole attaching machine, the combination of a turret arranged for rotation on a vertical axis, means for intermittently rotating the turret step by step, a plurality of upwardly facing pads on the turret arranged end to end about the periphery of the turret, and fluid-operated means for pressing shoes down upon the pads. 5
20. In a cement sole attaching machine, the combination of a plurality of pads, a carrier for presenting the pads in turn at an operating station with one of the longer sides of a pad adjacent to the operator, shoe holding means comprising a toe rest and a heel rest movable into position over each pad from that longer side of the pad which is remote from the operator, and manually operated means for moving the shoe holding means over the pad. 10
21. In a machine for cement sole attaching, the combination of a plurality of upwardly facing pads, a carrier for presenting the pads in turn at an operating station, shoe holding means movable into and out of position over the respective pads, fluid-pressure-operated means under control of the operator for operating each shoe holding means to press a shoe upon the corresponding pad while at the operating station, and means for automatically releasing the pressure of the holding means upon the shoe and pad when the pad next approaches the operating station. 15
22. In a cement sole attaching machine, the combination of a plurality of pads, a carrier for presenting the pads in turn at an operating station, shoe holding devices movable into and out of position over the respective pads, fluid-pressure-operated means under control of the operator for operating each shoe holding means to press a shoe upon the corresponding pad while at the operating station, and means operated by movement of the carrier for releasing the pressure of the holding means upon the shoe and pad when the pad next approaches the operating station. 20
23. In a cement sole attaching machine, the combination of a rotatable turret, a plurality of pads on the turret, a corresponding number of shoe engaging devices each movable outwardly of the turret from a position in which it is not over a pad into a position over the pad, means for moving each shoe engaging device over its pad at the operating station and causing relative movement of the shoe engaging device and the pad to apply sole attaching pressure to a shoe and sole, and means for automatically relieving pressure on the shoe on the pad which is next to come to the operating station. 25
24. In a cement sole attaching machine, the combination of a turret mounted for rotation about a vertical axis, a plurality of pads on the turret, shoe engaging devices each movable from a location out of position over the corresponding pad into pressing position over the pad, and operator-controlled means independent of rotation of the turret for causing the shoe engaging devices each in turn to press a shoe against the corresponding pad, and means for automatically relieving pressure on a shoe other than the one to which pressure is being applied. 30
25. In a cement sole attaching machine, the combination of a turret, a plurality of pads on the turret, shoe engaging devices movable into and out of position over the pads, operator-con- 35
- trolled means for moving each shoe engaging device in turn over its corresponding pad, for causing the shoe engaging devices each in turn to press a shoe against the corresponding pad and for causing rotation of the turret, and means operated by the turret for relieving pressure on a shoe other than that to which pressure is being applied. 40
26. In a cement sole attaching machine, the combination of a rotatable turret, a plurality of pads on the turret arranged with their long axes tangent to the direction of rotation of the turret, shoe engaging devices initially not over the pads and movable into position each over one of the pads, operator-controlled means for causing the shoe engaging devices each in turn to press a shoe against the corresponding pad, and automatic means for relieving pressure upon a shoe other than the one to which pressure is being applied. 45
27. In a cement sole attaching machine, the combination of a rotatable turret, a plurality of pads on the turret arranged with their long axes tangent to the direction of rotation of the turret, a plurality of shoe engaging devices initially not over the pads and each movable into position over one of the pads, operator-controlled means for causing the shoe engaging devices each in turn to press a shoe against the corresponding pad and for causing rotation of the turret, and means operated by rotation of the turret for relieving pressure upon the shoe which has been longest under pressure. 50
28. In a cement sole attaching machine, the combination of a rotatable turret, a plurality of pads on the turret arranged with their long axes tangent to the path of rotation of the turret, a plurality of shoe engaging devices initially not over the pads and each movable into position over one of the pads, and operator-controlled means for moving each shoe engaging device in turn into position over its corresponding pad for causing the shoe engaging devices in turn to press a shoe against the corresponding pad and for causing rotation of the turret. 55
29. In a cement sole attaching machine, the combination of a plurality of pads, a carrier movable to present the pads in turn at an operating station, a plurality of shoe holding devices one for each of the pads and movable into and out of position over the respective pads, fluid-pressure-operated means for relatively moving each shoe holding device and the corresponding pad to press the shoe and sole together while the pad is at the operating station, a valve having an inlet and an exhaust position associated with each fluid-pressure-operated means, manually operated means for moving each valve in turn when the valve is at the operating station to inlet position and for causing fluid under pressure to be supplied to said fluid-operated means, and means controlled by movement of the carrier for turning to outlet position that valve which is being carried to the operating station. 60
30. In a cement sole attaching machine, the combination of a rotatable turret, a plurality of upwardly facing pads on the turret, a plurality of shoe engaging devices each movable into and out of position over the corresponding pad, fluid-operated means for causing the shoe engaging devices in turn to press a shoe against a pad at an operating station and to maintain pressure upon the pad until, due to rotation of the turret, the pad has nearly completed a rotation, a valve controlling admission and exit of fluid for each 65
- 70
- 75

- fluid-operated means, means for setting each valve in inlet position at the operating station, and means for automatically turning each valve to outlet position as it approaches the operating station.
31. In a cement sole attaching machine, the combination of a rotatable turret, a plurality of upwardly facing pads on the turret arranged with their long axes tangent to the direction of rotation of the turret, a plurality of shoe engaging devices movable outwardly of the turret in position over the respective pads, and means for operating the shoe engaging devices in turn to press a shoe against a pad and maintain pressure thereon until the pad, due to rotation of the turret, has nearly completed a rotation, and means for automatically releasing the pressure on the shoe.
32. In a cement sole attaching machine, the combination of a rotatable turret, a plurality of upwardly facing pads on the turret, each pad being arranged with its long dimension extending in the direction of rotation of the turret, a plurality of shoe engaging devices each movable outwardly of the turret into position over a pad, means for operating the shoe engaging devices in turn to press a shoe against a pad and maintain pressure thereon until the pad, due to rotation of the turret, has nearly completed a rotation, and means operated by rotation of the turret for relieving the pressure of the shoe engaging devices.
33. In a cement sole attaching machine, the combination of a turret mounted for rotation about a vertical axis, a plurality of pads on the turret, a plurality of shoe engaging devices one for each of the pads, means independent of the rotation of the turret for operating the shoe engaging devices in turn to press a shoe against the corresponding pad and maintain pressure thereon until the pad, due to rotation of the turret, has nearly completed a rotation, and means operating without special attention on the part of the operator for then releasing said pressure.
34. In a machine for cement sole attaching, the combination of a turret arranged for rotation on a vertical axis, a plurality of upwardly facing pads on the turret, and a plurality of shoe engaging devices each arranged to move radially of the turret into and out of position over a shoe on a pad and to move bodily toward and from the pad in a rectilinear path.
35. In a machine for cement sole attaching, the combination of a turret arranged for rotation on a vertical axis, a plurality of upwardly facing pads on the turret, a plurality of shoe engaging devices each movable into and out of position over the corresponding pad and movable bodily toward and from the pad, a treadle for moving each shoe engaging device in turn over a pad, and power-operated means controlled by said treadle to effect said bodily movement of the shoe engaging devices.
36. In a cement sole attaching machine, the combination of a turret arranged for rotation on a vertical axis, a plurality of pads on the turret, a plurality of shoe engaging devices arranged to swing into and out of position over the pads about axes located below the pads, means for guiding the shoe engaging devices toward and from the pads, power-operated means for effecting movement of each shoe engaging device in turn toward the corresponding pad, and manually operated means for first moving each shoe en-
- gaging device over its pad and then setting the power-operated means in operation.
37. In a machine for cement sole attaching, the combination of a turret arranged for rotation on a vertical axis, a plurality of upwardly facing pads arranged with a longer side of the pad toward the turret edge, a corresponding number of shoe engaging devices carried by the turret and each arranged to move laterally of the pad and outwardly radially of the turret from a position at one side of the pad where it is not over the pad into position over one of the pads, and means for moving the shoe engaging devices to apply pressure to the shoes and soles on the pads.
38. In a cement sole attaching machine, the combination of a turret arranged for rotation on a vertical axis, a plurality of pads on the turret arranged with a side toward the turret edge, shoe engaging means for the respective pads, said means being supported on an axis extending under the pads and lengthwise thereof, and a fluid-operated reciprocatory member for operating the shoe engaging means to press shoes upon the pads.
39. In a machine for cement sole attaching, the combination of a turret arranged for rotation about a vertical axis, a plurality of upwardly facing pads on the turret, a corresponding number of shoe engaging devices carried by the turret and arranged to move into and out of position over the pads, manually operated means for moving each shoe engaging device in turn into position over the corresponding pad, means for moving the shoe engaging devices in turn to apply pressure to a shoe on the pad, and means for controlling said pressure applying means by movement of said manually operated means.
40. In a cement sole attaching machine, the combination of a turret arranged for rotation on a vertical axis, a plurality of pads on the turret, a plurality of shoe engaging devices one for each pad, a reciprocable member connected with each shoe engaging device and operable to press a shoe upon the corresponding pad, fluid-operated means for actuating said member, a pump for supplying fluid under pressure to said fluid-operated means, and manually operated means for controlling the pump.
41. In a cement sole attaching machine, the combination of a turret arranged for rotation on a vertical axis, a plurality of pads on the turret arranged with a side toward the turret edge, a shoe engaging means for each of the pads, each of said means being supported on an axis extending under its respective pad and lengthwise thereof, a fluid-operated plate located between each axis and its respective pad, and means for exerting fluid pressure on said plate to force the shoe engaging means toward the pad.
42. In a cement sole attaching machine, the combination of a turret arranged for rotation on a vertical axis, a plurality of pads on the turret, a plurality of shoe engaging devices one for each of the pads, each of said devices being supported on a member extending under its respective pad and lengthwise thereof, a plate connected with each member, means located between the plate and the pad for exerting fluid pressure on said plate to force the shoe engaging device toward the pad, and manually operated means for controlling operation of said fluid-pressure-exerting means.
43. In a machine for cement sole attaching, the

5 combination of a rotatable turret, a plurality of pads on the turret, means for rotating the turret to present the pads in turn at an operating station, a plurality of shoe engaging devices one for each pad, a plurality of fluid-pressure-operated devices for operating the respective shoe engaging devices in turn to press shoes against the respective pads, and a pump carried by the turret for supplying fluid to said fluid-pressure-operated devices.

10 44. In a machine for cement sole attaching, the combination of a rotatable turret, a plurality of pads on the turret, means for rotating the turret to present the pads in turn at an operating station, a plurality of shoe engaging devices one for each pad, a plurality of fluid-pressure-operated devices for operating the respective shoe engaging devices in turn to press shoes against the respective pads, a stationary tank containing liquid, 15 a pump carried by the turret and arranged to supply liquid under pressure to said fluid-pressure-operated devices, a clutch for controlling the operation of the pump, and manually controlled means for operating the clutch.

20 45. In a cement sole-attaching machine, the combination of a turret arranged for rotation, a plurality of pads on the turret, a plurality of shoe engaging devices one for each pad, a plunger connected with each shoe engaging device and 25 operable to press a shoe upon the corresponding pad, liquid-operated means for actuating the plunger, a pump carried by the turret for supplying liquid under pressure to said liquid-operated means, means for supplying liquid to said pump 30 in all positions of rotation of the turret, and means for operating the pump.

40 46. In a machine for cement sole attaching, the combination of a rotatable turret, a plurality of pads on the turret, means for rotating the turret to present the pads in turn at an operating station, a plurality of shoe engaging devices one for each pad, a plurality of fluid-pressure-operated devices one for operating each shoe engaging device to press a shoe against the pad, a pump 45 carried by the turret for supplying fluid to said fluid-pressure-operated device, and manually operated means for controlling the pump and the rotation of the turret.

50 47. In a cement sole attaching machine, the combination of a rotatable turret, a plurality of pads on the turret, means for rotating the turret to present the pads in turn at the operating station, a plurality of shoe engaging devices one for each pad, a plurality of fluid-pressure-operated devices one for operating each shoe engaging device to press a shoe upon the pad, a stationary 55 tank containing a liquid, a pump carried by the turret and arranged to draw liquid from the tank and supply it under pressure to said fluid-pressure-operated devices, a clutch for controlling operation of the pump, a clutch for controlling rotation of the turret, and a single manually operated means for controlling both clutches.

60 48. In a cement sole attaching machine, the combination of a rotatable turret, a plurality of pads on the turret, a plurality of shoe engaging devices each movable in position over one of the pads, a plurality of liquid-pressure-operated means one for each of the pads, each operating to 65 press a shoe engaging device and a pad together, means carried by the turret for producing liquid pressure to operate said liquid-pressure-operated means, and a stationary tank for supplying liquid to said pressure producing means.

70 49. In a cement sole attaching machine, the

combination of a rotatable turret, a plurality of pads on the turret, a plurality of shoe engaging devices one for each of the pads, a plurality of liquid-pressure-operated devices each arranged to press a shoe engaging device and its pad together, a pump carried by the turret for rotation therewith, a stationary tank for supplying liquid to said pump, and a conduit from said pump arranged to dip in the liquid of said tank in any position of rotation of the turret.

19

5 50. In a cement sole attaching machine, the combination of a plurality of pads, a carrier for presenting the pads in turn at an operating station, shoe holding means movable into position over each pad, manually operated means for moving each shoe holding means in turn over the corresponding pad, power-operated means for moving each holding means in turn to apply pressure to a shoe, and connections for controlling the power-operated means by movement of the manually operated means.

15 51. In a machine for cement sole attaching, the combination of a plurality of upwardly facing pads, a carrier for presenting the pads in turn at an operating station, a plurality of shoe holding means movable into and out of position over the respective pads, a plurality of fluid-pressure-operated means, one for operating each shoe holding means, power-operated means mounted on the carrier for producing fluid pressure for operating said fluid-pressure-operated means, and means for automatically releasing the pressure of the holding means upon the shoe and pad when the pad next approaches the operating station.

25 52. In a machine for cement sole attaching, the combination of a plurality of upwardly facing pads, a carrier for presenting the pads in turn at an operating station, means for intermittently moving the carrier, a plurality of shoe holding means each movable into and out of position over its respective pad, a plurality of fluid-pressure-operated means, one for operating each shoe holding means, power-operated means for producing fluid pressure for operating said fluid-pressure-operated means, means for intermittently operating said fluid-pressure-producing means to operate each fluid-pressure-operated means in turn and for moving the carrier, and means operated by movement of the carrier for stopping the pressure producing means and the carrier.

35 53. In a cement sole attaching machine, the combination of a plurality of pads, a carrier for presenting the pads in turn at an operating station, power-operated means for moving the carrier intermittently, a plurality of shoe holding devices movable into and out of position over the respective pads, fluid-pressure-operated means one for each of the pads, each operating to press a shoe on the corresponding pad while 40 at the operating station, and manually operated means for moving each holding device in turn over the shoe on the corresponding pad, said means operating upon further movement to set in operation the fluid-pressure-operated means and the carrier moving means.

45 54. In a cement sole attaching machine, the combination of a rotatable turret, means for rotating the turret, a plurality of pads on the turret, a plurality of shoe engaging devices each movable 50 into pressing position over the corresponding pad, a plurality of fluid-pressure-operated means, one for relatively operating each shoe engaging device and the corresponding pad to apply pressure to the shoe, power-operated fluid pressure produc-

75

ing means carried by the turret and connected to each of said fluid-operated means, operator-controlled means for setting said pressure producing means into operation, and means controlled by rotation of the turret for stopping the pressure producing means.

55. In a cement sole attaching machine, the combination of a rotatable turret, a plurality of pads on the turret, means for rotating the turret 10 to present each pad in turn at an operating station, a plurality of shoe engaging devices each movable outwardly of the turret into position over the corresponding pad, fluid-pressure-operated means for causing the shoe engaging devices in 15 turn to press a shoe against a pad, a single valve for each fluid-operated means arranged in one position of the valve to admit fluid pressure to the fluid-pressure-operated means and prevent exit of fluid therefrom, and in another position to permit 20 exit of fluid therefrom and prevent admission of fluid thereto, means for supplying fluid pressure to all of said valves, operator-controlled means at the operating station for turning each valve in turn to admit fluid to said fluid-pressure-operated means, and means operated by rotation 25 of the turret for turning that valve to exit position when the next shoe approaches the operating station.

56. In a cement sole attaching machine, the combination of a turret mounted for rotation about a vertical axis, a plurality of pads on the turret, means for rotating the turret, a plurality of shoe engaging devices, one for each of the 30 pads, fluid-pressure-operated means for each pad operating to effect relative movement of the pad and shoe engaging devices to press them together, means for supplying pressure to all of the fluid-operated devices, a valve for each fluid-operated device for controlling inlet of fluid to 35 and exit of fluid from each fluid-operated device, and manually operated means for setting each valve in turn in inlet position at the operating station and for causing operation of said pressure supplying means.

40 57. In a cement sole attaching machine, the combination of a pad, and two pairs of sole engaging members substantially fixed as to movement longitudinally of the pad and each pair 45 movable bodily laterally of the pad to engage the edge face of the forepart of a sole located on the pad.

58. In a cement sole attaching machine, the combination of a pad, members oppositely movable laterally of the pad, a pair of gages on each 55 of said members to engage the edge face of the forepart of a sole located on the pad, means tending to urge said members toward a sole on the pad, and means for retracting the members to permit a sole to be placed between them.

60 59. In a cement sole attaching machine, the combination of a pad, shoe engaging means movable laterally of the pad to engage a shoe on opposite sides thereof, and an extensible sheet connecting the shoe engaging means on one side 65 of the shoe with the shoe engaging means on the other side of the shoe.

60. In a cement sole attaching machine, the combination of a pad, a pair of shoe gages at each side of the pad, a resilient sheet connecting the pair of shoe gages, means for separating the pairs of gages against the tension of said sheet to permit a shoe to be placed between them, and means for terminating the action of the separating means thereby permitting the pairs of gages

75 to be drawn toward the shoe by contraction of said resilient sheet.

61. In a cement sole attaching machine, the combination of a pad, shoe engaging means on opposite sides of the pad, a resilient sheet connecting the shoe engaging means, means for tensioning the sheet to separate the shoe engaging means, and operator-controlled means for terminating the action of the tensioning means thereby permitting the shoe engaging means to engage the shoe on opposite sides in response to contraction of the sheet.

62. In a machine for operating on shoes, the combination of a sheet of resilient material, and a plurality of shoe engaging members connected thereto and arranged to be separated when the sheet is stretched and to move toward each other when the stretching force is no longer applied.

63. In a cement sole attaching machine, the combination of a pad, sole engaging members 20 movable laterally of the pad to engage the edge face of a sole on opposite sides thereof, and an extensible sheet connecting a sole engaging member on one side of the shoe with a sole engaging member on the other side of the shoe.

64. In a cement sole attaching machine, the combination of a pad, a pair of sole gages at each side of the pad, a resilient sheet connecting the pairs of sole gages, means for separating the pairs of gages against the tension of said sheet to permit a sole to be placed between them, and means permitting the pairs of gages to be drawn toward the sole by contraction of said resilient sheet.

65. In a cement sole attaching machine, the combination of a pad, sole gages on opposite sides 35 of the pad, a rubber sheet connecting the sole gages, means for tensioning the rubber sheet to separate the gages, and operator-controlled means for permitting the gages to engage the sole in response to contraction of the sheet.

66. In a cement sole attaching machine, the combination of a pad, a resilient sheet extending across the forepart of the pad, and sole engaging members having portions extending through the sheet to prevent the sole from extending under 45 the sole engaging members.

67. In a cement sole attaching machine, the combination of a pad, a resilient sheet extending across the forepart of the pad, and sole engaging members connected to the sheet so that a sole 50 cannot extend between the members and the sheet.

68. In a machine for operating on shoes, the combination of a sheet of resilient material, and a pair of gage members carried thereby arranged 55 to be separated when the sheet is stretched and to move toward each other when the stretching force is no longer applied.

69. In a machine for operating on shoes, the combination of a pad, a sheet of resilient material resting on the pad, and a pair of gage members carried by the sheet and arranged to be separated when the sheet is stretched and to move toward each other when the stretching force is no longer applied.

70. In a cement sole attaching machine, the combination of a sheet of resilient material, a pair of gage members carried thereby, means for stretching the sheet to separate the gage members, and means for releasing the stretching force 70 to permit the gage members to approach each other.

71. In a cement sole attaching machine, the combination of a sheet of resilient material, a gage member carried thereby, and means for 75

stretching the sheet to move the gage member into an inoperative position.

72. In a cement sole attaching machine, the combination of a pad, a rubber sheet extending across the forepart of the pad and having its marginal portions reinforced, sole engaging members connected to the sheet and having portions extending through the reinforced portion of the sheet to prevent a sole from extending under the sole engaging means, and means for tensioning the sheet to separate the sole engaging members.

73. In a cement sole attaching machine, the combination of a pad, members movable laterally of the pad toward and from the edge face of the forepart of a sole located on the pad, a pair of sole gages carried by each of the members, means tending to urge the members toward a sole on the pad, automatic means for separating the members to permit a sole to be placed between the gages, and operator-controlled means for causing movement of the members in opposite directions so that one pair of gages will engage the sole on one side and the other pair will engage the sole on the other side.

74. In a cement sole attaching machine, the combination of a pad box, a pad in the box, a rubber sheet extending across the forepart of the pad, means engaging the lateral margins of the sheet and movable laterally to tension the sheet, and sole engaging members carried by the tensioning means and extending through the sheet to prevent a sole from extending under the sole engaging members.

75. In a cement sole attaching machine, the combination of a pad box, a pad in the box, a rubber sheet extending across the forepart of the pad, means at the two sides of the box for clamping the marginal portions of the sheet, a pair of combined shoe and sole engaging members carried by each clamping means, and means for separating the clamping means to stretch the sheet and separate the pairs of shoe and sole engaging members to permit introduction of a sole between said pairs, contraction of said sheet serving to press the sole engaging members against the sole, the shoe engaging members being positioned thereby for the reception of a shoe and acting to locate the forepart of the shoe with respect to the forepart of the sole.

76. In a cement sole attaching machine, the combination of a pad box, a pad in the box, a rubber sheet extending across the forepart of the pad, means for clamping the marginal portions of the sheet at the two sides of the box, a pair of combined shoe and sole engaging members carried by each clamping means, power operated means for separating the clamping members to stretch the sheet and separate the pairs of shoe and sole engaging members to permit introduction of a sole between said pairs, contraction of said sheet serving to press the sole engaging members against the sole, the shoe engaging members being positioned thereby for the reception of a shoe and acting to locate the forepart of the shoe with respect to the forepart of the sole, and operator-controlled means for permitting contraction of said rubber sheet.

77. In a cement sole attaching machine, the combination of a pad box, a pad in the box, members arranged to engage the edge face of a sole located on the pad, means for pressing a shoe and sole together, and means operated by such pressure for locking the sole engaging means against movement away from the sole.

78. In a cement sole attaching machine, the

combination of a pad, an extensible sheet extending across the forepart of the pad, means for stretching the sheet laterally of the pad, sole engaging members carried by said sheet, and means between the sheet and the pad in position to receive pressure of the shoe and lock the sole engaging members in sole engaging position.

79. In a cement sole attaching machine, the combination of a pad, an extensible sheet extending across the forepart of the pad, means for stretching the sheet laterally of the pad, sole engaging members carried by said sheet, and a perforated plate between the sheet and the pad in position to receive pressure of the shoe to lock the sole engaging members in sole engaging position.

80. In a cement sole attaching machine, the combination of a pad, a resilient sheet extending across the forepart of the pad, means for stretching the sheet laterally of the pad, sole engaging members carried by said sheet, and a perforated plate connected to each sole engaging member and located between the sheet and the pad whereby pressure between the pad and shoe will cause the material of the sheet to enter the perforations and to prevent movement of the sole engaging members.

81. In a cement sole attaching machine, the combination of a pad box, a pad in the box, members arranged to engage the edge face of a sole located on the pad, shoe gages carried by said sole engaging means, means operated by forward pressure of the shoe against said gages for locking the sole engaging means against movement away from the sole, and means for pressing the shoe and sole together.

82. In a cement sole attaching machine, the combination of a pad to receive a sole, gages movable laterally of the sole to engage the opposite sides of the forepart of the sole, shoe gages carried by the sole gages for locating the forepart of a shoe in proper position with respect to the forepart of the sole, and means operated by forward pressure of the shoe upon the shoe gages for locking the gages against movement away from the shoe.

83. In a cement sole attaching machine, the combination of a pad to receive a sole, gages movable laterally of a sole on the pad to engage opposite sides of the forepart of the sole, shoe gages carried by the sole gages for locating the forepart of a shoe in proper relation to the forepart of the sole, a fixed toothed locking member, and toothed members carried by the gages, forward pressure of the shoe upon the gages causing slight forward movement of the gages and consequent engagement of the teeth and locking of the gages.

84. In a cement sole attaching machine, the combination of a pad, a shoe engaging abutment movable into position over the pad from that side of the pad which is remote from the operator, and shoe locating gages arranged to move into shoe locating position in conjunction with movement of the shoe engaging means over the pad.

85. In a machine for cement sole attaching, the combination of a pad, a shoe engaging abutment movable into position over the pad from that side of the pad which is remote from the operator, means for operating the shoe abutment to press a shoe upon the pad, shoe locating means movable over the pad to engage the rear portion of a shoe upon the pad, and connections between the shoe locating means and the shoe

engaging means for causing the locating means to engage opposite sides of the rear portion of the shoe when the shoe abutment is moved into position over the pad.

5 86. In a cement sole attaching machine, the combination of a pad, a shoe engaging abutment movable into position over the pad, shoe locating means arranged to move laterally of the pad into shoe engaging position, means tending to 10 move said locating means into shoe engaging position, and manual means for moving the shoe abutment over the pad and for controlling movement of said locating means toward the shoe.

15 87. In a cement sole attaching machine, the combination of a pad, a shoe engaging abutment movable into position over the pad, means for operating the shoe abutment to press a shoe upon the pad, locating means movable inwardly of the pad to engage the sole of a shoe upon the 20 pad, and manual means for moving the shoe abutment over the pad for controlling the movement of the locating means toward the shoe and for controlling the means for operating the shoe abutment to press a shoe upon the pad.

25 88. In a cement sole attaching machine, the combination of a pad, a shoe engaging abutment movable into and out of position over the pad, means for locating relatively the forepart of a shoe and the forepart of a sole on the pad, and 30 a single manually operated means for moving the shoe abutment over the pad and for causing the locating means to engage the forepart of a sole upon the pad.

35 89. In a cement sole attaching machine, the combination of a pad, a shoe engaging abutment movable into and out of position over the pad, means for locating relatively the forepart of a shoe and the forepart of a sole on the pad, means for engaging the rear part of a sole irrespectively of its length for locating it centrally 40 of the pad, means movable laterally of the pad for engaging opposite sides of the rear part of a shoe and locating it properly with respect to the rear part of the sole, and means operated in conjunction with movement of the shoe abutment over the pad to cause the means for engaging the rear part of the shoe to move toward each other and to locate the shoe with respect to the sole.

45 90. In a cement sole attaching machine, the combination of a pad, a shoe engaging abutment movable into and out of position over the pad, means for locating relatively the forepart of a shoe and the forepart of a sole on the pad, and 50 a single manually operated means for moving the shoe abutment over the pad and for causing the locating means to engage the forepart of the sole on the pad and for controlling the application of pressure to the shoe.

55 91. In a cement sole attaching machine, the combination of a pad, shoe pressing means movable into and out of position over the pad, means for locating relatively the forepart of a shoe and the forepart of a sole on the pad, a pin for engaging the rear part of a sole irrespectively of its length and for locating it centrally of the pad, members arranged for movement to engage opposite sides of the rear part of a shoe to locate the rear part of the shoe with respect to the rear 60 part of the sole, and means operated in conjunction with movement of the pressing means over the pad to cause said members so to operate.

65 92. In a cement sole attaching machine, the combination of a pad, means for engaging a recess in the rear part of a sole and holding it

from movement laterally of the pad, means for engaging opposite sides of the rear part of a shoe placed on the sole, and means for operating said shoe engaging means to shift the rear part of the shoe and locate it properly with respect to the sole. 5

93. In a cement sole attaching machine, the combination of a pad, means for engaging on its longitudinal median line the rear part of a sole placed on the pad, means for engaging opposite sides of the rear part of a shoe placed on the sole, and means for operating said shoe engaging means to shift the rear part of the shoe to locate the same properly with respect to the sole. 10

94. In a cement sole attaching machine, the combination of a pad to receive a shoe sole, a pin mounted for movement longitudinally of the sole and vertically with respect to the sole to enable the pin to engage a hole in the sole and locate it with respect to the pad, and shoe engaging members movable to engage opposite sides of the rear part of the shoe for locating the rear part of the shoe with respect to the rear part of the sole. 15

95. In a cement sole attaching machine, the combination of a pad to receive a shoe sole which 20 has a hole therein, a tongue arranged for movement longitudinally of the sole, and a pin carried by the tongue for engaging the hole in the sole. 25

96. In a cement sole attaching machine, the combination of a pad to receive a shoe sole, said 30 sole being provided with a hole, a tongue arranged for movement longitudinally of the sole and also for movement toward and from the sole, a pin carried by the tongue for engaging the hole in the 35 sole, and means for holding the tongue in a raised inoperative position and in an operative position with the pin engaging the hole in the sole.

97. In a cement sole attaching machine, the combination of a pad to receive the shoe sole, 40 shoe engaging means movable into an outer position over the pad and operable to press a shoe upon the pad, shoe locating means arranged to engage an end portion of the shoe, and means rendered operative upon movement of the shoe 45 engaging means over the shoe for causing the shoe locating means to operate.

98. In a cement sole attaching machine, the combination of a pad to receive a sole, a sole locating device movable longitudinally of the 50 pad and arranged to swing from an elevated position over the sole to sole engaging position, a pin carried by said locating device for engaging an opening in the rear part of the sole to position the heel end centrally of the pad, and a spring 55 for holding said locating device either in elevated position or sole engaging position irrespective of its location longitudinally of the pad.

99. In a cement sole attaching machine, the combination of a pad to receive a sole, locating 60 means for positioning the heel end of the sole centrally of the pad, said means being movable into and out of position over the pad about an axis extending transversely of the lengthwise dimension of the pad, and resilient means for holding 65 said locating means in either of the two positions into which it is movable.

100. In a cement sole attaching machine, the combination of a pad to receive a sole, means for locating the heel end of the sole centrally of the 70 pad, said means being arranged to be swung into and out of sole engaging position heightwise of the pad, and yieldable means for holding said locating means out of sole engaging position, for permitting said engaging means to be moved 75

manually into sole engaging position, and for holding said locating means in said sole engaging position.

101. In a cement sole attaching machine, the combination of a pad arranged to receive a sole, means movable toward and away from the sole about an axis extending transversely of the pad for positioning the heel end of the sole on the pad, gages movable laterally of the pad to engage opposite sides of the forepart of the sole, and a resilient member cooperating with the heel end positioning means for holding said means against the sole during the operation of said gages.

102. In a machine for cement attaching soles to shoes, the combination of a pad to receive a sole, means arranged to swing into and out of operative position heightwise of the pad for positioning the heel end of the sole, and a spring for holding said positioning means either in one or the other of its two positions.

103. In a cement sole attaching machine, the combination of a pad to receive a sole having a hole in the lateral center of its rear part, and a pin for engaging the hole in the sole, said pin being mounted for movement longitudinally of the sole, for movement heightwise of the sole to engage the hole, and restrained from movement laterally of the sole.

104. In a cement sole attaching machine, the combination of a pad to receive a shoe sole, a pin for engaging a hole in the rear end of the sole, said pin being movable longitudinally and vertically but not transversely with respect to the pad, engagement of the pin with the hole in the sole acting to locate the rear part of the sole centrally with respect to the pad, and shoe engaging members movable to engage opposite sides of the rear part of the shoe and locate the rear part of the shoe with respect to the rear part of the sole.

105. In a cement sole attaching machine, the combination of a pad to receive a sole having a hole in the lateral center of its rear part, a pin for engaging the hole in the sole, said pin being mounted for free movement longitudinally of the sole and for movement heightwise of the sole to engage the hole but restrained from movement laterally of the sole, members for engaging the opposite sides of the forepart of the sole, means for locking said members in sole engaging position, shoe gages on said members for locating the forepart of a shoe in proper position with respect to the forepart of the sole, and shoe locating members movable equally and oppositely to engage the rear part of the shoe and locate it properly relatively to the rear part of the sole already located by the pin.

106. In a cement sole attaching machine, the combination of a pad to receive a sole having a hole in the lateral center of its rear part, a pin for engaging the hole in the sole, said pin being mounted for movement longitudinally of the sole, for movement heightwise of the sole to engage the hole, and restrained from movement laterally of the sole, gages movable laterally of the sole to engage the opposite sides of the forepart of the sole, shoe gages carried by the sole gages for locating the forepart of the shoe in proper position with respect to the forepart of the sole, means operated by forward pressure of the shoe upon the shoe gages for locking the gages against movement away from the shoe, and means for locating the rear part of the shoe relatively to the rear part of the sole already located by the pin.

107. In a cement sole attaching machine, the combination of a movable carrier, a plurality of pads on the carrier, means for moving the carrier to present the pads in turn at an operating station, sole and shoe gages for each of the pads for determining the relative positions of the shoe and sole, means normally urging said gages into operative position, means at the operating station for moving and holding said gages in inoperative position, and operator-controlled means for permitting movement of the gages into operative position.

108. In a cement sole attaching machine, the combination of a movable carrier, a plurality of pads on the carrier, means for moving the carrier to present the pads in turn at an operating station, sets of sole and shoe gages for each of the pads for determining the relative positions of the shoe and sole, means normally urging said gages into operative position, means adjacent to the operating station and operated by movement of the carrier for moving a set of said gages into inoperative position, and operator-controlled means for permitting movement of that set of gages into operative position when the set is located at the operating station.

109. In a cement sole attaching machine, the combination of a pad, a bail extending longitudinally of the pad and arranged to swing into and out of position over a shoe on the pad about an axis extending longitudinally of the pad, and shoe engaging devices carried by the bail.

110. In a cement sole attaching machine, the combination of a pad box, a pad in the box, a bail extending longitudinally of the box and pivoted at the ends of the box, and a toe rest and heel rest carried by the bail.

111. In a cement sole attaching machine, the combination of a pad to receive a sole, a shoe engaging device arranged to swing about an axis parallel to the lengthwise dimension of the pad into and out of position over a shoe on the pad, fluid-pressure-operated means for actuating said device to press a shoe and sole against the pad, and means for adjusting the position of the forepart of the pad so that it will conform substantially to the angle of the forepart of the shoe before the pressure is applied.

112. In a cement sole attaching machine, the combination of a sectional pad to receive a sole and shoe, a bail arranged to swing about an axis parallel to the lengthwise dimension of the pad into and out of position over a shoe on the pad, engaging members on the bail for engaging the forepart of the shoe and the cone of a last in the shoe to press the shoe and sole against the pad, fluid-pressure-operated means for actuating said bail, manually operated means for adjusting the position of the forward section of the pad so that it will conform substantially to the angle of the forepart of the shoe bottom, and means for locking said adjusting means in position when pressure is applied to the sole and shoe.

113. In a cement sole attaching machine, the combination of a yielding pad to receive a shoe and sole, means for pressing a shoe upon a sole located upon the pad, a tilting support for the forepart of the pad, a latch for holding the support in various tilted positions to vary the positions of the forepart of the pad with respect to the shank portion thereof, and means operated by pressure of the shoe upon the pad for preventing release of said latch.

114. In a cement sole attaching machine, the combination of a pad box, a yielding pad in the

75 75

box, means for pressing a shoe and sole upon the pad, a support for the forepart of the pad comprising a plate having a rib extending transversely thereof approximately at the ball line of the pad, 5 said rib engaging a groove in the box, a hand piece on the plate extending beyond the front wall of the box to be accessible to the operator, and a fixed member having teeth to engage the hand piece to hold the plate in various positions 10 of adjustment, the rib being displaced from the groove to permit release of the hand piece when no pressure is on the pad and being held in the groove to prevent release of the hand piece when pressure is applied to the pad by the shoe.

15 115. In a cement sole attaching machine, a pad, shoe engaging means arranged for movement into and out of operative position over a shoe upon the pad, a treadle for causing movement of the shoe engaging means into operative position 20 over the pad, means controlled by said treadle for relatively moving the pad and shoe engaging means to apply pressure to a shoe and sole, and means for disconnecting the treadle from the shoe engaging means prior to operation of the 25 pressure applying means.

116. In a cement sole attaching machine, a rotatable turret, a plurality of pads on the turret, shoe engaging means movable into and out of operative position over the respective pads, power-operated means for imparting partial rotations to the turret to present the pads in turn at an operating station, and a treadle constructed and arranged to cause movement of the shoe engaging devices in turn into operative position to 35 become disconnected therefrom and then to set said power means in operation.

117. In a cement sole attaching machine, the combination of a pad, shoe engaging means, shoe and sole locating means initially out of operative 40 position to permit placing a sole and shoe on the pad, a treadle for causing movement of the locating means into operative position, means controlled by said treadle for relatively moving the pad and shoe engaging means to apply pressure 45 to the shoe and sole, and means for disconnecting the treadle from the locating means prior to the application of pressure to the shoe and sole.

118. In a cement sole attaching machine, the combination of a turret, a plurality of pads 50 mounted on the turret, a plurality of shoe engaging devices one for each pad, means for relatively operating the pads and devices in turn to place shoes under pressure, shoe and sole locating mechanism associated with each pad and initially 55 out of operative position, a treadle for causing movement of the positioning mechanism into operative position, power means for rotating the turret, means for disconnecting the treadle from the positioning means, and means thereafter operated by the treadle for setting the turret rotating 60 means in operation.

119. In a cement sole attaching machine, the combination of a turret, a plurality of fluid-containing bags on the turret, a shoe holdown for 65 each bag so arranged that upon inflation of a bag pressure will be applied to a shoe and sole between the bag and its holdown, a power-operated pump for forcing fluid into said bag, a valve for controlling admission of fluid to the bag, and a 70 treadle arranged first to open the valve and then to set the pump in operation.

120. In a cement sole attaching machine, the combination of a pad, shoe engaging means for holding a shoe on the pad, fluid-pressure-operated 75 means for relatively moving the pad and the

holding means to apply pressure to the shoe, a power-operated pump for applying pressure to said fluid-pressure-operated means, a valve controlling the admission of pressure to the fluid-pressure-operated means, and a treadle arranged 5 first to turn said valve to inlet position and then to set the pump in operation.

121. In a cement sole attaching machine, the combination of a turret, a plurality of pads on the turret, a shoe holdown for each pad, a fluid-operated bag for each pad arranged upon inflation to effect relative movement of the pad and hold-down to apply pressure to a shoe and sole on the pad, a power-operated pump for forcing fluid into said bag, a valve for controlling the admission of 15 fluid to the bag, and a treadle arranged first to open the valve and then to set the pump in operation.

122. In a cement sole attaching machine, the combination of a turret, a plurality of pads on 20 the turret, a shoe engaging device for each pad, fluid-pressure-operated means for relatively operating each pad and shoe engaging device to apply pressure to a shoe and sole, a valve controlling admission of fluid to the fluid-pressure-operated means, means for imparting intermittent 25 partial rotations to the turret, and a treadle having connections first to open said valve and then to cause rotation of the turret.

123. In a cement sole attaching machine, the 30 combination of a pad, a shoe engaging device mounted for movement into and out of operative position over a shoe on the pad, fluid-pressure-operated means for relatively moving the pad and shoe engaging device to apply pressure to a shoe and sole, a valve for controlling admission of fluid to said means, a power-operated 35 pump for supplying fluid under pressure, and a treadle arranged to move said shoe engaging device into operative position over the shoe to 40 open said valve and then to set the pump in operation.

124. In a cement sole attaching machine, the combination of a turret, a plurality of pads on 45 the turret, shoe engaging devices, one for each 50 pad, movable into and out of operative position over a shoe on the pad, fluid-pressure-operated means for relatively moving each pad and shoe 55 engaging device, to apply pressure to a shoe and sole on the pad, a valve for admitting fluid under pressure to each of said fluid-operated devices, means for imparting intermittent partial rotations to the turret, and a treadle constructed and arranged upon operation to move each shoe 60 engaging device in turn into operative position to open the valve of the corresponding pad and then to cause rotation of the turret.

125. In a cement sole attaching machine, the combination of a turret, a plurality of pads on 65 the turret, shoe engaging devices one for each 70 pad movable into and out of operative position over a shoe on the pad, fluid-pressure-operated means for relatively moving each pad and shoe 75 engaging device to apply pressure to a shoe and sole on the pad, a valve for admitting fluid under pressure to each of said fluid-operated devices, power-operated means for supplying fluid under pressure to said fluid-operated devices, means for imparting intermittent partial rotations to the 80 turret, and a treadle constructed and arranged upon operation to move each shoe engaging device in turn into operative position, to open the valve of the corresponding pad, and then to cause operation of said power-operated 85 means and rotation of the turret.

126. In a cement sole attaching machine, a pad, shoe engaging means arranged for movement into and out of position over a shoe upon the pad, shoe and sole positioning devices movable into and out of operative position, a treadle for causing movement of the shoe engaging means into operative position over the pad, means controlled by the treadle for moving the shoe and sole positioning devices into operative position, means controlled by said treadle for relatively moving the pad and shoe engaging means to apply pressure to a shoe and sole, and means for disconnecting the treadle from the shoe engaging means and the positioning devices prior to operation of the pressure applying means. 5
127. In a cement sole attaching machine, the combination of a pad, a shoe engaging device mounted for movement into and out of operative position over a shoe on the pad, positioning means for relatively locating a shoe and sole on the pad and movable into and out of operative position, fluid-pressure-operated means for relatively moving the pad and shoe engaging device to apply pressure to a shoe and sole, a power-operated pump for supplying fluid under pressure to said fluid-operated means, and a treadle arranged to move said shoe engaging device into operative position over the shoe to cause movement of the positioning means into operative position. 20
128. In a cement sole attaching machine, the combination of a turret, a plurality of pads on the turret, shoe engaging devices one for each pad movable into and out of operative position over a shoe on the pad, means for relatively moving each pad and shoe engaging device to apply pressure to a shoe and sole on the pad, shoe and sole positioning devices movable into and out of operative position to engage the shoe and sole, means for imparting intermittent partial rotations to the turret, and a treadle constructed and arranged upon operation to move each shoe engaging device in turn into operative position 35
- 40 to cause movement of the shoe and sole positioning devices into operative position and then to cause rotation of the turret.
129. In a cement sole attaching machine, a rotatable turret, a plurality of pads on the turret, shoe engaging means movable into and out of operative position over the respective pads, shoe and sole locating means movable into and out of operative position with respect to a shoe and sole on each pad, power-operated means for 45 imparting partial rotations to the turret to present the pads in turn at an operating station, power means for relatively operating each pad and shoe engaging means to apply pressure to a shoe, and a treadle constructed and arranged 50 to cause movement of the shoe and sole locating means in turn into operative position, movement of the shoe engaging devices in turn into 55
- operative position, to become disconnected therefrom, and then to set said power means in operation to apply pressure to the shoe and to rotate the turret. 60
130. In a cement sole attaching machine, the combination of a pad, a shoe engaging device, shoe and sole locating devices mounted for movement into and out of operative position with respect to a shoe and sole on the pad, fluid-pressure-operated means for relatively moving the pad and shoe engaging device to apply pressure to a shoe and sole, a valve for controlling admission of fluid to said means, a power-operated pump for supplying fluid under pressure, and a treadle arranged to cause movement of 10 said shoe and sole locating devices into operative position over the shoe to open said valve and then to set the pump in operation. 13
131. In a cement sole attaching machine, the combination of a turret, a plurality of pads on the turret, a plurality of shoe and sole locating devices one for each pad, fluid-pressure-operated means for relatively operating each pad and shoe engaging device to apply pressure to a shoe and sole, a valve controlling admission of fluid 20 to the fluid-pressure-operated means, means for imparting intermittent partial rotations to the turret, and a treadle having connections first to cause operation of the locating devices and open said valve and then cause rotation of the turret. 25
132. In a cement sole attaching machine, the combination of a turret, a plurality of pads on the turret, a shoe engaging device for each pad, fluid-pressure-operated means for relatively operating each pad and shoe engaging device to apply pressure to a shoe and sole, shoe and sole positioning devices movable into and out of operative position with respect to a shoe and sole on each pad, means for imparting intermittent partial rotations to the turret, and a treadle having connections first to cause movement of the 30 positioning devices into operative position and then to cause application of pressure to the shoe and rotation of the turret. 35
133. In a cement sole attaching machine, the combination of a turret, a plurality of pads mounted on the turret, a plurality of shoe engaging devices one for each pad, means for relatively operating the pads and devices in turn to place shoes under pressure, shoe and sole locating mechanism associated with each pad and initially out of operative position, a treadle for causing movement of the locating mechanism into operative position, power means for rotating the turret, means for disconnecting the treadle from the positioning means, means operated by the treadle for thereafter setting the turret rotating means in operation, and means operated by the turret for moving each locating mechanism in turn to inoperative position. 40
